UNITED STATES PATENT OFFICE

2,060,384

AUTOMATIC SHOE POLISHING MACHINE

Harry T. Shearer, Waynesboro, Pa., assignor to
 Automatic Machine Manufacturing Company,
 Baltimore, Md., a corporation of Delaware

Application March 27, 1934, Serial No. 717,637

21 Claims. (Cl. 15—35)

This invention relates to automatic shoe polishing machines.

An important object of the invention is to provide a novel automatic machine operative for applying polishing material to the shoes and subsequently polishing them.

A further object is to provide an automatic machine of the character referred to wherein polish is automatically applied to brushes which in turn transfer the polish to the shoes, whereupon the polish applying brushes move out of contact with the shoes and polishing brushes move into contact therewith to perform the polishing operation.

15 A further object is to provide a traveling polishing unit for each shoe operative in an orbital path around each shoe and each including polish-applying and polishing brushes, automatic operating and controlling means being provided for applying polish to each shoe during 20 one or more complete movements of each polishing unit around the shoe, and then for moving the polish-applying brushes out of engagement with the shoes while the polishing brushes remain 25 in contact therewith during one or more complete movements of the polishing units around the shoes.

A further object is to provide a machine of the character referred to which is operative automatically for performing the successive operations of brushing the shoes to remove dust and dirt therefrom, applying polish to the shoes, and then efficiently polishing the shoes, after which the apparatus automatically stops pending further operation which may be initiated through the insertion of a coin in a suitable coin control mechanism.

30 A further object is to provide a novel toe polishing mechanism wherein brushes traveling across the toe portions of the shoes are caused to first apply polish to the shoes and then to perform the polishing operation thereon.

A further object is to provide toe polishing units each embodying a plurality of brushes one 40 of which applies polishing material to the toe portions of one shoe and another of which performs the polishing operation, and to provide automatic means for causing the brushes referred to to successively perform their operations.

A further object is to provide toe polishing units of the character referred to wherein the brushes of each unit are mounted for movement about a vertical axis and are provided with means 45 for oscillating them within limited ranges of

movement for performing the polish-applying and polishing operations, and to further provide means for bodily moving each brush about its vertical axis to first move the polish-applying brush of each unit into contact with the corresponding shoe and then to move the polishing brush into such operative position.

5 A further object is to provide toe polishing means of the character referred to having suitable mechanism for constantly oscillating the brushing units about their vertical axes, and to provide automatic means for bodily moving the units in the manner and for the purpose stated, means being further provided prior to the movement of the polish-applying brush into engagement with the shoe for transmitting polishing material thereto.

A further object is to provide novel polish-applying means for the toe polishing units whereby each polish-applying brush, during its initial movement oscillates over and in engagement with the polish supplying means, the latter device being so constructed as to efficiently supply polish to each polish-applying brush and to permit such brush to pass out of engagement therewith without any splashing of the polishing material.

20 A further object is to provide a novel shoe polishing apparatus embodying traveling brush units automatically operative around orbital paths corresponding generally in shape to the shape of each shoe, and to provide automatic means for polishing the toe portions of the shoes, means being further provided for moving the toe polishing units out of the path of travel of the traveling units as the latter move in the portions 25 of their orbital paths adjacent the toes of the shoes.

A further object is to provide an apparatus of the general character just referred to wherein the traveling brush units initially operate to clean the shoes by brushing dirt and dust therefrom prior to the application of polish thereto, and wherein the toe polishing units are maintained out of operative position throughout the cleaning operation and are released for normal operation after the cleaning operation has been completed.

30 A further object is to provide automatic means operative upon the completion of the cleaning operation by the traveling brush units for supplying polish to the polish-applying brushes of the traveling units and for moving such brushes into engagement with the shoes and maintaining them in such engagement during 35

one or more complete movements of each traveling brush unit around its orbital path.

A further object is to provide an apparatus for performing the several functions referred to in cyclic sequence, and to provide a single source of power for the various parts of the apparatus.

A further object is to provide novel pumping means for supplying polishing material to the polish-applying brushes, the polish supplying means for the polish-applying brush of each traveling unit being automatically operative during contact of such brush with the shoe for supplying polish thereto.

A further object is to provide novel coin control means for the apparatus, and to provide means associated therewith for preventing the insertion of a coin in the apparatus when the supply of polishing material is exhausted.

A further object is to provide means operative through the insertion of a coin in the coin control apparatus for initiating the operation of the driving motor and for closing a holding circuit therefor to maintain the operation of the motor throughout the series of cyclic operations of the apparatus, means being further provided for stopping operation of the motor when the polishing operations have been completed.

A further object is to provide means for stopping the operation of the motor with the toe polishing units in inoperative position and the traveling units at the forward ends of the shoes to permit the next user of the apparatus to readily place his feet in position to permit the shoes to be polished.

Other objects and advantages of the invention will become apparent during the course of the following description.

In the drawings I have shown one embodiment of the invention. In this showing:

Figure 1 is a perspective view of the apparatus, Figure 2 is an elevation of the same, parts being shown in section.

Figure 3 is a plan view of the apparatus complete, all of the remaining views of the drawings being shown without the casing structure and associated parts,

Figure 4 is a horizontal sectional view taken substantially on line 4—4 of Figure 5,

Figure 5 is a vertical longitudinal sectional view taken substantially on line 5—5 of Figure 4,

Figure 6 is a rear elevation,

Figure 7 is a longitudinal sectional view on line 7—7 of Figure 4,

Figure 8 is a similar view on line 8—8 of Figure 4, the motor being omitted,

Figure 9 is an enlarged plan view,

Figure 10 is a transverse vertical sectional view taken substantially on line 10—10 of Figure 9,

Figure 11 is a similar view on line 11—11 of Figure 5,

Figure 12 is a detail fragmentary sectional view on line 12—12 of Figure 11,

Figure 13 is an enlarged sectional view through the driving and controlling mechanisms for one of the traveling brush units, the parts, for the purpose of illustration, being shown in positions which they will not normally assume during the operation of the apparatus.

Fig. 14 is a horizontal sectional view taken substantially on line 14—14 of Figure 10,

Figure 35 is a similar view of a cam for raising and lowering the toe brush units out of the path of travel of the traveling units, shown in starting position,

Figure 36 is a similar view of an interference cam for holding the toe brush units elevated during the initial or cleaning operation of the traveling units, shown in starting position,

Figure 37 is a similar view of a cam for actuating the pump for supplying polish to the polish-applying brushes of the toe polishing units, shown in starting position,

Figure 38 is a detail sectional view on line 38—38 of Figure 7,

Figure 39 is a diagrammatic view of the electrical control circuits and associated parts, and,

Figure 40 is a tabular representation of the successive cyclic operations of the apparatus.

Referring to Figure 1, illustrating the complete apparatus in operative condition, the numeral 10 designates a casing as a whole in which most of the operating elements of the apparatus are housed. At the forward end of the apparatus, a seat 11 is supported on a pedestal 12 secured to the upper wall 13 of the casing. To one side of the seat 11, the top of the casing 10 is offset downwardly and provides a step 14 to facilitate entrance into the seat 11. At the forward end of the apparatus and at the side opposite the step 14 an upstanding casing 15 is arranged, and this casing houses a portion of the coin control mechanism, to be referred to later.

The casing 10 is provided adjacent its rear end with upstanding side walls 16 closed at the 75

top as at 17. At the forward end of the wall 17 a depending front flange 18 is secured, and beneath the top wall 17 the toe brushing units to be described are operative.

5 Foot rests 19 are arranged forwardly of the seat 11 and project partially beneath the top wall 17 as shown in Figure 3. The supporting means for the foot rests and the operating means associated therewith will be referred to in detail later. Traveling brush units are indicated as a whole by the numeral 20 in Figure 1, and each of these units travels in an orbital path around the adjacent foot rest 19 to clean the shoes, apply polish thereto, and then polish the 15 shoes, and this operation will be referred to in detail later. The traveling brush units automatically stop adjacent the forward ends of the foot rests 19 after each polishing operation is completed, the traveling units being indicated in 20 such position in Figure 1 beneath the cover 17. The toe polishing units are maintained in elevated position at such time, and with the parts in the positions illustrated in Figure 1 it will be apparent that anyone desiring to utilize the apparatus may occupy a position on the seat 11 with the feet resting upon the foot rests 19, whereupon the coin control mechanism may be operated upon the insertion of the proper coin.

Referring to Figures 4, 5 and 7, the numeral 30 21 designates the main frame of the apparatus as a whole, and this frame is preferably cast as an integral unit. The frame includes projecting integral feet 22 adapted to rest on an angle iron rectangular sub-frame 23, forming the 35 base of the outer casing 10. The sub-frame 23 is provided adjacent each corner thereof with an upwardly offset caster seat 24 carrying casters 25 by means of which the apparatus may be readily moved from place to place. In this connection, it will be noted that the particular form 40 of the casing 10 and the means for supporting the apparatus for movement do not form important parts of the apparatus and have been eliminated in all of the parts except Figures 1, 45 2 and 3.

As shown in Figures 4 and 9, a suitable motor 26 is supported on a lower base portion 27 and has its shaft coupled as at 27 to a drive shaft 28. This shaft extends into a housing 29 carried by the base 21 and is journaled in suitable 50 bearings 30. Within the housing 29, the shaft 28 carries a worm 31 (see Figure 7) and this worm meshes with a worm wheel 32 carried by a main longitudinal drive shaft 33 extending 55 throughout the length of the base 21. A bearing 34 in the adjacent wall of the casing 29 supports one end of the main drive shaft 33 and the other end of this drive shaft is supported in a bearing 35 carried by a vertical wall 36 forming 60 a part of the main support 21. The bearing 35, more specifically, is supported in a vertical web 37 (see Figure 6) forming a part of the wall 36. Intermediate its ends, the shaft 33 is supported in a bearing 38 carried by a partition 65 wall 39 forming a part of the main frame 21.

The shaft 33 carries a worm 40 (see Figures 5 and 12) meshing with a worm wheel 41 having its hub secured to a transverse shaft 42, as shown in Figure 4. The shaft 42 is supported 70 in suitable bearings 43 carried by portions of the main frame 21, and the wheel 41 operates in a housing 44 the lower section of which is formed integral with the main frame 21. This housing is divided and has a cover portion 45, as shown 75 in Figure 5.

The shaft 42 carries a pinion 46 meshing with a gear 47. The gear 47 is formed integral with a pinion 48, being connected thereto by a hub 49, and this hub is freely rotatable on a shaft 50. This shaft is journaled in bearings 51 carried respectively by a wall 52 forming part of the main frame 21 and by an outer wall 53 of the main frame. The pinion 48 meshes with a gear 54 carried by a shaft 55 supported in suitable bearings 56 and 57, the latter being carried by 10 the side wall 58 of the main frame opposite the wall 53 previously described. The various elements connected to the shaft 55 or operated thereby will be referred to in detail later.

As previously stated, the gear 47 and pinion 15 48 are freely rotatable on the shaft 50 and operate to transmit power from the shaft 42 to the shaft 55. This transmission of power is continuous, as will become apparent, while intermittent drive means is provided between the shafts 20 42 and 50. Referring to Figures 4, 11 and 12, it will be noted that a Geneva gear is provided for driving the shaft 50 from the shaft 42. This gear includes the usual star wheel 59 carried by a shaft 60 journaled in bearings 61 carried by 25 the casing walls 52 and 53, as shown in Figure 11. A hub 62 is secured to the shaft 42 and has the usual arcuate cut away portion 63 employed in gearing of this character. An arm 64 projects radially from the hub 62 and carries a roller 30 65 at its free end engageable in the radial recesses 66 of the star wheel. The Geneva gear is of conventional construction, as will be obvious, and need not be further described in detail.

The shaft 60 carries a pinion 67 and this pinion is connected to the star wheel 59 by an integral hub 68. This pinion meshes with a gear 69 secured to the shaft 50 to transmit intermittent movement to this shaft through the Geneva gear. Outwardly of the frame wall 53, the shaft 40 50 carries a cam 70 shown in detail in Figure 32 of the drawings. The cam 70 is operated by the intermittent or step by step movement referred to and functions to control the positions of the elements of the toe brush units to be referred to. 45 The apparatus makes fourteen complete cycles of operation automatically, and at the starting of the apparatus, the cam occupies the position shown in Figure 32.

The cam 70 is provided with integral walls 50 71 and 72 forming a cam groove indicated as a whole by the numeral 73. A roller 74 is arranged in the cam groove 73 and is connected to one end of a slidable arm 75. The cam 70 rotates in the direction of the arrow shown in 55 Figure 32, and the apparatus starts with the roller 74 in the position shown in such figure. The cam groove 73 includes three concentric portions respectively indicated by the numerals 76, 77 and 78. The concentric portion 76 extends from the point 79 to the point 80; the concentric portion 77 extends from the point 81 to the point 82; and the concentric portion 78 extends from the point 83 to the point 84. Intermediate the concentric portions referred to, the 60 cam is suitably shaped to form a continuous groove through which the roller 74 is adapted to travel. At one side, the cam 70 is provided with an integral lug 85 carrying a projecting pin 86 and the purposes of this pin will be referred 65 to later.

Referring to Figure 4 the numeral 87 indicates a guide carried by the side wall 53 of the main frame and supporting the bar 75 for rectilinear sliding movement. The end of the bar 75 oppo- 75

site the roller 74 is pivotally connected as at 98 to one end of a link 89. The other end of this link is pivotally connected as at 90 to one arm 91 of a bell crank lever. This lever is pivotally supported as at 92 to a top plate 93 forming a part of the main frame 21. The arm 91 projects through a cut away portion 94 of the frame structure, while the other arm 95 of the bell crank lever projects through a cut away portion 96 formed in the top plate 93.

The arrangement of the lever arm 95 is shown in Figures 4 and 5, it being noted that the lever arm curves upwardly in the latter figure and terminates in a bearing member 97. The bearing member 97 is also shown in Figure 6 and carries a vertical pin 98 rotatably supporting a roller 99. A crosshead 100 is transversely slidable in guides 101 carried by the end frame wall 36. The crosshead carries a projecting portion 102 at one end having a recess 103 facing downwardly and receiving the roller 99. It will be apparent that the rocking of the bell crank lever, by operation of the cam 70, transmits sliding movement to the crosshead 100, and this crosshead is maintained stationary during the periods of operation of the cam 70 in which the roller 74 is arranged in the concentric portions 76, 77 and 78 of the cam groove 73.

A lever indicated as a whole by the numeral 104 is pivoted intermediate its ends on a stub shaft 105 carried by a trunnion 106 and this trunnion is formed integral with the crosshead 100. A bearing 107 surrounds the stub shaft 105 to pivotally support the lever 104. This structure is clearly shown in Figures 5 and 6. The lower arm 108 of the lever 104 is pivotally connected as at 109 to a link 110. The opposite end of this link rotates about an eccentric stub shaft 111 carried by the main drive shaft 33 (see Figure 7) and a bearing 112 surrounds the stub shaft 111. It will be apparent that rotation of the main drive shaft 33 transmits oscillating movement to the lever 104 about the axis of the stub shaft 105, and this axis is shiftable to three positions by the cam 70 as previously stated, and for a purpose to be described.

Referring to Figures 5, 6 and 7, the numeral 113 designates a rack bar reciprocable transversely of the apparatus. This rack bar is pivotally connected as at 114 to one end of a link 115, and the opposite end of this link is pivotally connected as at 116 to the upper end 117 of the lever 104. A bracket 118 is bolted to the main frame and is provided with upstanding arms 119 and 120, the former of which is provided at its upper end with a guide 121 for the rack bar 113. The upper end of the arm 120 is provided with arms 122 the lower of which forms a part of a second guide for the rack bar 113. A plate 123 is secured to the arms 122 as shown in Figure 7, and forms the remaining portion of the other guide for the rack bar 113.

A shaft 124 extends vertically through the arms 122 and upper and lower integral pinions 125 and 126 surround the shaft 124, as shown in Figure 7. The pinion 126 meshes with the teeth of the rack bar 113 to be oscillated by the rack bar upon reciprocation thereof. This oscillation is transmitted to the toe brush units to be described.

Referring to Figures 4, 6 and 7, the numerals 127 and 128 designate a pair of vertically movable rods slidable in upper and lower guides 129 carried by the main frame. A plate or crosshead 130 extends between the rods 127 and 128, as shown in Figures 6 and 7, and this crosshead carries

bosses 131 secured to the respective bars 127 and 128.

The lower bosses 131 carry outstanding trunnions 132 to which are connected the lower ends of tension springs 133. The upper ends of these springs are connected to screws 134 projecting through bosses 135 carried by and projecting inwardly from the upper ends of brackets 136. These brackets are secured to extensions 137, forming a part of the main frame 21, as shown 10 in Figures 6 and 8. The springs 133 function to counterbalance the weight of the rods 127 and 128 and crosshead 130, and the elements to be described which are movable therewith.

A transverse connecting member 138 extends 15 across the top of the apparatus as shown in Figures 5 to 8 inclusive, and this member carries bosses 139 at its ends for receiving the upper ends of the rods 127 and 128, the bosses being secured thereto as will be apparent. The transverse 20 member 138 extends forwardly as shown in Figures 5, 7 and 8 and includes upper and lower walls 140 and 141 in which are arranged vertically aligned bearings 142. In the embodiment of the invention illustrated there are four sets of the 25 bearings 142 (see Figure 6) and shafts 143, 144, 145 and 146 are journaled in the respective sets of these bearings. Beneath the lower bearings 142, the outermost shafts 143 and 146 carry toe brush units respectively indicated as a whole by 30 the numerals 147 and 148.

Each toe brush unit includes a segmental plate 149 (see Figures 5, 8 and 38). It is preferred that each toe brush unit be provided with three segmental brushes 150, 151 and 152, and these 35 brushes are adapted to perform the respective functions of applying polishing material to the toe of the adjacent shoe, polishing the toe portion of the shoe, and then buffing or finishing the polished portions of the shoe. The latter brush of 40 course, is not essential to the proper operation of the machine, but its use is preferred in order that a high lustre may be provided, and accordingly the apparatus as illustrated employs such finishing brushes together with means for controlling 45 their operation.

The segmental plate of the toe brushing unit 147 is provided with a downwardly offset arcuate portion 153 arranged at the side of the plate opposite the brush elements referred to, as shown 50 in Figures 5 and 38. This arcuate plate portion 153 is provided with a segmental gear 154. As shown in Figures 5 and 6, an elongated sleeve 155 surrounds the rod 127 and the upper end of this sleeve is provided with a pinion 156 meshing 55 with the segmental gear 154. The sleeve 155 is suitably fixed against vertical movement with respect to the rod 127 and is vertically movable therewith. The means for moving the rods 127 and 128 vertically will be referred to in detail 60 later. An elongated pinion 157 is formed on the lower end of the sleeve 155 and meshes with the teeth of the pinion 125 throughout the range of vertical movement of the sleeve 155.

It will be apparent that reciprocation of the 65 rack bar 113 oscillates the sleeve 155 through the medium of the pinions 125 and 126, and accordingly oscillating movement is transmitted to the toe brushing unit 147 through the pinion 156 and segmental gear 154. Means are provided for transmitting such oscillating movement to the toe brush unit 148. Referring to Figures 6 and 9, the numeral 158 designates a gear carried by the shaft 143, and since the toe brush unit 147 is carried by the same shaft, it 75

will be apparent that the gear 158 and unit 147 oscillate with each other. The shaft 144 carries a similar gear 159 meshing with the gear 158 and the gear 159, in turn, meshes with a similar gear 160 carried by the shaft 145. The shaft 146 to which the toe brush unit 148 is secured, carries a similar gear 161, meshing with the gear 160. It will be apparent that the gears 158 and 160 turn in the same direction at a given time, while the gears 159 and 161 turn in the opposite direction at such time. Thus it will be apparent that the toe brush units 147 and 148 turn in opposite directions at a given time, and with the starting of the apparatus, both toe brush units are turned outwardly and occupy the position shown in Figure 9. It will be apparent that the gears 158 to 161 inclusive are arranged between the walls 140 and 141, and these walls form a housing 20 for the gears.

As previously stated, the brush 150 of each of the units 147 and 148 is operative for applying polishing material to the toe portions of the shoes, and automatic means are provided 25 for supplying such material to the brushes 150. Referring to Figures 6 and 22, the numeral 162 designates a polish supplying unit for supplying polishing material to the brushes 150. Each of these units embodies a hollow casing having an upper wall 162' slightly curved in the direction of movement of the brush 150 thereover, and the wall 162' is provided with an outlet orifice 163. The polish supplying units 162 are supported from the transverse top member 30 138 by means of brackets 163'. The apparatus is shown with the brushes 150 in the starting position in Figure 6, and it will be noted that these brushes are in position over the supply unit 162. Polishing material is supplied to the 35 units 162 through suitable pipes 164 and 165 leading from a pump unit 166 to be referred to in detail later. It will become apparent that as soon as the apparatus is placed in operation, the pump mechanism 166 operates to force 40 polishing material through the orifice 163 of each unit 162 where such material is picked up by the brushes 150. During such time, each of the brush units is being oscillated, and accordingly the polishing material will be spread over 45 the areas of the brushes 150.

As previously stated, the rods 127 and 128 are vertically movable and the purpose of such movement is to elevate the toe brush units to permit movement of the traveling brush units, to be described, around the forward portions of the shoes without interference by the toe brush units. The means for accomplishing such vertical movement of the toe brush units are illustrated in Figures 4, 5, 6 and 8. A cam wheel 55 167 is carried by the shaft 42 substantially centrally of the width of the apparatus and since the shaft 42 rotates at a constant speed during the entire operation of the apparatus, it will be apparent that the cam 167 likewise rotates continuously. The cam wheel 167 is provided with a segmental cam 168 concentric with the axis of the shaft 42 and operative in a manner to be described for elevating the toe brush units. Referring to Figure 4, the numeral 169 designates a transverse shaft journaled in bearings 60 170 carried by opposite side portions of the main frame 21. An arm 171 is secured at one end to the shaft 169 and is provided at its opposite end with a roller 172 engageable with the cam 168. 65 Two side arms 173 are secured at one end to

the shaft 169 and these arms have their other ends projecting through the end wall 36 of the main frame 21 as shown in Figures 5 and 6. The latter end of each arm 173 is pivotally connected as at 174 to a link 175. These links are pivotally connected as at 176 to suitable ears 177 preferably formed integral with the crosshead 130. Since the lugs 131 of the crosshead 130 are secured to the rods 127 and 128, it will be apparent that the rocking of the arms 171 and 173 will 10 transmit vertical movement to the rods 127 and 128, thus vertically moving the toe brush units.

As previously stated, several functions of the apparatus are controlled by the shaft 55. This shaft carries an interference cam 178 which lies 15 adjacent and in the plane of the cam 167. The shaft 55 is constantly driven through the transmission means previously described, including pinion 46, gear 47, pinion 48 and gear 54, but the speed of rotation of the shaft 55 is greatly 20 reduced below the speed of the shaft 42. As also previously stated, the apparatus performs fourteen cyclic operations in brushing, supplying polish and polishing the shoes, and the cam 167 rotates once during each cycle of operation, or fourteen times during a complete operation of the apparatus. On the other hand, the shaft 55, and consequently the cam 178 rotates only once during the complete operation 25 of the apparatus and the length of the interference cam 178 corresponds to the first two of the cyclic operations of the apparatus.

The arm 171 is provided with a short depending arm 179 (see Figures 5 and 11) and this arm carries a pin 180 on which is rotatably supported a roller 181 adapted to be engaged by the interference cam 178. Thus it will be apparent that the arm 171, and consequently the vertical position of the toe brush units, are controlled by both the cams 168 and 178. These 35 cams are shown in Figures 35 and 36 in the normal positions prior to the starting of the apparatus, under which conditions the toe brush units are elevated as shown, for example, in Figures 7 and 8. During the first two cycles 40 of operation of the apparatus the cam 168 rotates twice, but the adjacent end of the arm 171 will not be affected by the cam 168 since it will be held in lower position by the interference cam 178. Thus the toe brush units will be 45 held elevated throughout the completion of the first two cycles of operation, and it is during this time that the polish-applying brushes 150 for the toe brushing units will be oscillated in engagement with the polish supplying units 162, with 50 the polish pumping mechanism 166 in operation. During the first two cycles of operation, therefore, the polish-applying brushes 150 will be gathering polishing material preparatory to performing the next two cycles of operation during which period the brushes 150 will operate to apply the polish to the toe portions of the shoes, except during those portions of the third and 55 fourth cycles in which the traveling units to be described are moving around the forward ends of the shoes. During the periods of the third and fourth cycles in which the latter operation is taking place, the cam 168 holds the arm 171 in lower position, thus elevating the toe brush units to permit movement of the 60 traveling units without interference therewith.

Referring to Figures 5, 7 and 10, the numeral 182 designates a gear housing suspended from the plate 93 by a preferably integral sleeve 184. As more clearly shown in Figure 10, the casing 75

182 is provided with a lateral extension 185 through which the main drive shaft 33 extends, and this shaft is provided within the casing extension 185 with a worm 186. Opposite ends of 5 the casing extension 185 are preferably provided with suitable bearings 187. The worm 186 meshes with a worm wheel 188 within the gear casing 182, and this wheel is mounted on a vertical shaft 189 extending upwardly through the 10 sleeve 184. Suitable bearings 191 are mounted within the sleeve 184 to suitably support the shaft 189 for rotation, and the upper bearing 191 is adapted to act as a thrust bearing.

The upper end of the shaft 189 carries a pinion 193, and beneath this pinion the shaft 189 is surrounded by a hub 194 carrying a gear 195. In a manner to be described, the pinion 193 and gear 195 operate and control the traveling brush units. The traveling brush units are associated 20 with the respective foot rests 19 and these units are duplicates of each other.

In Figure 13 one of the brush units has been illustrated to show the driving and controlling means therefor to the best advantage. It should 25 be borne in mind in connection with this figure that it shows an arrangement of a number of the parts in positions which they never occupy in the actual operation of the machine and they have been shown in such positions solely for the 30 purpose of illustration. These elements, in themselves, are capable of assuming the positions illustrated, but do not assume such positions in normal operation for the reason that their positions normally are governed by certain guide 35 means to be referred to in detail later.

Since the traveling brush units are duplicates of each other, only one need be referred to in detail. Referring to Figures 10 and 13, the numeral 196 designates an integral depending boss 40 carried by the top frame plate 93, and this boss receives and supports the lower end of an elongated vertical sleeve 197. The lower end of the sleeve 197 may be slightly tapered to permit it to seat tightly within the boss 196 and it is 45 clamped in position by a lower nut 198. A second sleeve 199 surrounds the sleeve 197 above the plate 93 and is rotatable with respect to the sleeve 197. The sleeve 199 is supported at its lower end by a thrust bearing 200 carried by the 50 plate 93. At its lower end, the sleeve 199 carries an integral pinion 201 meshing with the gear 195, as shown in Figure 10. At a point spaced from its upper end, the sleeve 199 is shouldered as at 202 to support a hub 203, and this hub is clamped in position with respect to the 55 sleeve 199 by a nut 204. Beneath the point where it engages the shoulder 202, the hub 203 carries an enlarged depending cylindrical flange 205 which terminates at its lower end in a bevel 60 gear 206 for a purpose to be described.

Another sleeve 207 surrounds the sleeve 199 concentric therewith and has its upper end arranged within but freely rotatable with respect to the cylindrical flange 205. The lower end of 65 the sleeve 199 is shouldered as at 208 at the point where the pinion 201 is formed, and a thrust bearing 209 is arranged on the shoulder 208 to support the sleeve 207. A large gear 210 is formed integral with the sleeve 207 and meshes 70 with the pinion 193 as shown in Figure 10. The gear 210 accordingly is constantly rotatably by the pinion 193 and it forms a plate to support a shaft and gear carrier 211 as shown in Figure 13. Thus it will be apparent that the carrier 211 rotates as a unit with the gear 210, and it is this

action which transmits bodily movement to the traveling brush units to be described to cause them to travel in an orbital path around the shoes. Of course, it will be apparent that only one of the traveling brush units is disclosed in 5 Figure 13, and as previously stated, these units and their driving and controlling means are identical.

Each sleeve 197, supporting the foot rest 19 is provided throughout the greater portion of its 10 length with a bore 212 adapted to receive a vertically slideable spindle 213. This spindle is shown in Figures 4, 8, 10 and 20 and has been omitted from Figure 13 for the purpose of illustration. At a point spaced below the associated foot rest 19, each sleeve 197 is provided with diametrically opposite vertical slots 214 through which extends a pin 215. This pin has its opposite ends extending into a ring 216, as clearly shown in Figure 20. A crosshead sleeve 217 surrounds the 20 sleeve 197 with its lower end in sliding and rotating engagement therewith and the upper end of the sleeve 217 is enlarged as at 218 to form an annular recess 219 in the bottom of which the ring 216 is arranged. A thrust bearing 220 is 25 arranged in the recess 219 in engagement with the top of the ring 216, and a nut 221 is threaded in the upper end of the recess 219.

As shown in Figures 8 and 16, the sleeve 217 is 30 provided with a lateral extension 222 formed integral therewith and elongated transversely of the axis of the sleeve 197. This extension cooperates with a cover plate 223 to form a guide for a slideable bar 224. The plate 223 is secured to the extension 222 by suitable screws 225 (see 35 Figures 16 and 19) and the extension 222, cover plate 223 and sleeve 217 form a crosshead vertically movable with the spindle 213, such vertical movement being transmitted to the crosshead sleeve 217 by the pin 215. The crosshead extension 222 and its cover plate carry a pair of longitudinally offset rollers 226 supported by pins 227 and these rollers 226 act as bearings for the bar 224 which is adapted to reciprocate through the extension 222 for a purpose to be described. 40

Referring to Figures 4, 8, 11 and 34, the numeral 228 designates a cam carried by the shaft 55. This cam is provided with a trackway 50 the greater portion 229 of which is concentric with the axis of the shaft 55. The trackway 229 receives a roller 230 carried by one end of a lever 231. The arm 231 is formed integral with a hub 232 secured to a shaft 233. This shaft extends transversely of the apparatus as shown in Figure 4 and is rotatably supported by bearings 234 carried by the frame 21. Another arm 235 is formed integral with the hub 232 and this arm is pivotally connected at its free end to the lower end of one of the spindles 213 as at 236. Adjacent the opposite side of the apparatus another arm 237 is provided with a hub 238 also secured to the shaft 233 and the free end of the arm 237 is pivotally connected as at 238' to the lower end of the other spindle 213, as shown in Figure 10. 55

It will be apparent that the concentric portion 229 of the cam groove of the cam 228 maintains the free end of the arm 231 in lower position, thus holding the spindles 213 elevated during the greater portion of the operation of the apparatus. The cam groove referred to has a 60 second concentric portion as shown in Figure 34 forming the low portion of the cam and extending from the point 239 to the point 240. The parts of the apparatus are shown in Figure 34 in the starting position, and as previously stated, 65 70 75

the first two cycles of operation of the apparatus are for the purpose of causing the traveling brush units to travel twice around the shoes to brush them, after which the polish-applying brushes of the traveling units come into operation to apply polish to the shoes. It is the purpose of the cam 228 to control the polish-applying means and this result is accomplished when the roller 230 passes into the low portion of its associated cam groove. This operation will be referred to in detail later.

Each shaft and gear carrier 211, as previously described and as shown in Figure 13, is supported on one of the gears 210 to be bodily rotated therewith. The carrier 211 includes a horizontal integral cylindrical portion 241 having bearings 242 arranged in opposite ends thereof for rotatably supporting a shaft 243. At one end, this shaft carries a bevel pinion 244 meshing with the pinion 206. A similar bevel pinion 245 is carried by the other end of the shaft 243. At its end opposite the pinion 244, the carrier is provided with spaced parallel arms 249, and each of these arms is provided with bearings 247 supporting a vertical shaft 248. This shaft carries a sleeve 249, keyed or otherwise secured thereto, and oppositely facing bevel gears 250 and 251 are carried by the sleeve 249. The bevel gear 250 meshes with the pinion 245 to be driven thereby and this action obviously takes place independently of the bodily rotation of the carrier 211 with the gear 210.

A second carrier 252 is associated with the carrier 211. The carrier 252 is provided with spaced arms 253 arranged above the respective arms 246 and provided with bearings 254 in which the shaft 248 is arranged. It will be apparent that the carrier 252 is free to swing with respect to the carrier 211 about the axis of the shaft 248. The carrier 252 is provided with a cylindrical portion 255 carrying bearings 256 to rotatably support a shaft 257. This shaft carries a bevel pinion 258 at one end meshing with the bevel gear 251. It will be apparent that the shafts 243 and 257 will be rotated in the same direction at approximately the same speed. In this connection it will be noted that the pinions 245 and 258 are substantially equal in size, and the same is true of the bevel gears 250 and 251.

50. The carrier 252 is provided with integral arms 259 which carry bearings 260 rotatably supporting a shaft 261. A bevel pinion 262 is carried by the shaft 257 and meshes with a similar gear 263 carried by the shaft 251. The shaft 261 extends upwardly a substantial distance above the upper arm 259 and is important in determining a number of functions of the associated traveling brush unit. For example, the shaft 261 transmits bodily movement to its associated traveling brush unit to cause it to travel in an orbital path around one of the shoes and its transmits rotational movement to the polishing and polish-applying brushes. These operations will be described in detail later.

55. Referring to Figures 5, 8, 9, 13 and 16, the numeral 264 designates a plate carried by the sleeve 197 just above the carriers 211 and 252. The plate 264 is substantially the shape illustrated in Figures 9 and 16 and is provided at its edge with a flange portion 265 forming the inner limit of an orbital pathway 266. The plate 264 is preferably split longitudinally as at 267 to permit it to slide freely over the sleeve 197 to be placed in position, and includes a split central collar portion 268 adapted to be clamped about

the sleeve 197 by bolts 269. The plate 264 obviously is stationary with the sleeve 197. A top plate 270 is supported upon upstanding arms 271 formed integral with the main frame 21, and secured thereto by suitable screws 272 or other fastening elements. The plate 270 is provided with an inner flange 273 equidistantly spaced from the flange 265 and plate 264 and defines with the latter the orbital trackway 266.

5 Except for the point where the shaft 261 (see 10 Figure 13) and the associated parts of each traveling brush unit are arranged in the trackway 266, each trackway is closed by a series of plates 274 connected at their adjacent ends by pivot pins 275. Each of the pivot pins 275 extends downwardly below the plates 274 to support a roller 276 preferably mounted on the corresponding pin 275 by anti-friction bearings 277. During the operation of the traveling brush units, the rollers 276 travel around the orbital trackway 266 to guide the plates 274 whereby the latter act as closures for the trackway 266.

15 As shown in Figure 13, the shaft 261 is provided with a roller 278 preferably mounted thereon with anti-friction bearings and operable 20 in the trackway 266. Above the roller 278, an elongated plate 279 (see Figure 15) has one end 25 surrounding the shaft 261 and mounted thereon with anti-friction bearings, as shown. Adjacent its opposite end, the plate 279 is provided with a stub shaft 280 on the lower end of which is 30 mounted a roller 281 operable in the trackway 266. Beneath the plate 279 a bearing plate 282 is arranged and is held in position with respect to the plate 279 by bosses 283 depending therefrom. The plates 264 and 270, forming the trackway 266, are provided on their upper surfaces adjacent such trackway with broadened surfaces 284 forming bearing surfaces for the plate 282. It will be noted that the plate 274 of 40 the chain of plates arranged over the trackway 266 and adjacent the plate 279 is not connected thereto. Such connection is unnecessary and the freedom of movement between the elements referred to prevents any binding action between 45 the walls of the trackway 266 and the rollers operable therein.

45. An arm 285 has one end surrounding the shaft 261 and connected thereto by anti-friction bearings as shown in Figure 13, just above the plate 50 279. Outwardly of such plate the arm 285 turns downwardly and then extends horizontally outwardly away from the shaft 261 and is provided with a stub shaft 286 carrying a roller 287 operable in the trackway 266. An extension 288, carried by the arm 285, is provided with a pin 289 to which the adjacent plate 274 is connected. As shown in Figures 14 and 15, the arm 285 is provided with an arm 290 extending laterally inwardly with respect to the trackway 266. A 60 square shaft 291 has its lower end secured in the free end of the arm 290 and the upper end of this shaft is secured in the free end of an arm 292 corresponding in shape and position to the arm 290 and having its inner end surrounded and connected by anti-friction bearings to the shaft 261 adjacent the upper end thereof. A detailed showing of the connection of the square shaft 291 to the arms 290 and 292 is shown 65 in Figure 18. A vertical arcuate connecting member 292' is formed integral with the arms 290 and 292 (see Figure 14) and accordingly it will be apparent that the latter arms are fixed with respect to each other.

70 A crosshead 293 is vertically slidable on the 75

square shaft 291 as shown in Figures 14, 16 and 18. Adjacent its upper end, the crosshead 293 carries an offset boss 294 elongated transversely of the body of the crosshead and carrying a pin 5 295 rotatably supporting a roller 296. The purpose of this roller is to control the polish-applying brush to be referred to for causing the latter to apply polish to the side portions of the shoes during the third and fourth cyclic operations of the 10 apparatus. This operation will be described in detail later. Adjacent its lower end, the crosshead 293 carries a projecting fork 297 and a pin 298 passes through this fork to pivotally connect it to the adjacent end of the slideable rod 224. 15 The arms 279 and 285 form portions of the traveling brush units and accordingly move around the orbital trackways 266, and accordingly each square shaft 291 is constantly moving toward and away from the corresponding spindle 213. 20 Accordingly the slideable arm 224 is provided to compensate for varying distances between each square shaft 291 and its corresponding spindle 213, while at the same time, vertical movement of the two spindles 213 will transmit vertical 25 movement to the two crossheads 293 of the traveling brush units to cause the rollers 296 to operate in the manner previously stated, namely, to cause the polish-applying brushes to apply polish to the shoes. 30 Referring to Figures 13, 14 and 15, the numeral 299 designates a housing as a whole arranged to one side of the shaft 261. This housing includes upper and lower arms 300 surrounding the shaft 261 in spaced parallel relation and supported on the shaft by suitable anti-friction bearings. Thus 35 it will be apparent that the housing 299 is free to swing about the axis of the shaft 261. The housing 299 includes a bottom wall 301 and below this wall the housing 299 is provided with an enlarged depending skirt portion 302. A sleeve 303 projects downwardly through the bottom portion of the housing 299 and carries a gear 304 at its lower end within the skirt portion 302. The bottom wall 301 of the housing 299 is provided 40 with a pair of depending bosses 305 each of which supports a stub shaft 306, as shown in Figures 13 and 15. The stub shafts 306 rotatably support pinions 307 and 308, meshing with each other, and the pinion 307 meshes with the gear 304. The shaft 261 carries a gear 309 which 45 meshes with the pinion 308. The housing 299 is provided with a vertical spindle 310 journaled at its upper end in a bearing 311. The lower end of the spindle 310 is 50 reduced as at 312 and is rotatable and slideable in the sleeve 303 which forms a bearing therefor. A clutch element 313 is formed on the upper end of the sleeve 303 and a coacting clutch element 314 is splined on the spindle 310. A spring 315 normally urges the clutch member 314 downwardly, but means to be described are provided for holding the clutch element 314 in its upper inoperative position except during the third and 55 fourth cyclic operations of the apparatus during which polish is applied during the orbital movements of the traveling brush units. The upper end of the spindle 310 is provided with a polish-applying brush 316, and since this brush is rotated by the spindle 310, it will be apparent that 60 the brush 316 is inoperative except during the two cyclic operations in which the clutch elements 313 and 314 are in operative engagement. As previously stated, the housing 299 is free to 65 swing about the axis of the shaft 261, and it will 70 75

become apparent that during the third and fourth cyclic operations referred to, the housing 299 will be swung inwardly with respect to the trackway 266 to bring the brush 316 into engagement with the shoe to apply polishing material thereto. 5 During the remaining twelve cyclic operations, the brush 316 will be held out of engagement with the shoe by means to be described.

At the side of the shaft 261 opposite the housing 299 a second housing 317 is arranged, and this 10 housing is provided with upper and lower arms 318 surrounding the shaft 261 and supported with respect thereto by suitable anti-friction bearings. The housing 317 accordingly is free to swing about the axis of the shaft 261. The 15 upper end of this shaft carries a polishing brush 322 as shown, for example, in Figures 6, 9 and 20 13. Beneath the arm 320, the housing 317 is provided with a gear housing 323 integral with the arm 320. The bottom of this housing may be covered by a plate 324 secured thereto by screws 325. The lower end of the spindle 321 25 may be reduced as at 326 to extend through a suitable opening in the plate 324. Within the housing 323, the spindle 321 is provided with a gear 327 meshing with the gear 309, as shown 30 in Figures 13 and 15. It will be apparent from 35 the latter figure that the gears 304 and 327 rotate in the same direction, and the same accordingly is true of the brushes 316 and 322.

A sleeve 328 surrounds the shaft 261 and is provided at its lower end with an outstanding flange 329 (see Figure 13) having a plurality of circumferentially spaced radial openings 330 for a purpose to be described. A torsion spring 331 surrounds the lower portion of the sleeve 328 and has its inner end secured thereto. The outer 40 end 332 of the spring 331 engages against one edge of the housing 317 and accordingly tends to swing this housing in a clockwise direction as viewed in Figure 14, thus tending to swing the brush 322 inwardly. A second and shorter sleeve 45 333 surrounds the portion of the sleeve 328 above the spring 331 and is provided at its lower end with an outstanding annular flange 334 having a plurality of circumferentially spaced openings 335 similar to the openings 330 in the flange 329. 50 One each of the openings 330 and 335 receives a pin 335', and these pins project through suitable openings 336' formed in the arm 292' and function to retain the springs 331 and 336 under tension. 55

A spring 336 surrounds the sleeve 333 and has its inner end secured to the sleeve 333 as shown in Figure 14. The outer end of the spring 336 is connected to a boss 337' formed integral with a plate 338 closing the inner side of the gear 60 housing 299 as shown in Figure 14. Thus the spring 336 tends to swing the housing 299 in a counter-clockwise direction, and accordingly tends to swing the brush 316 inwardly. This brush, as will become apparent, is the polish-applying brush of the traveling units and is held outwardly in the position shown in Figure 14 during all of the operation of the apparatus except the third and fourth cycles. The plate 338' 65 carries a cam 337 (see Figures 14, 16 and 17). This cam is substantially arcuate in plan, and has its inner edge 338 forming the cam proper and engageable with the top of the roller 296. 70

Referring to Figures 13 and 14, the numeral 75

339 designates a worm carried by the shaft 310. This worm meshes with a worm wheel 340 carried by a shaft 341 journaled in suitable anti-friction bearings carried by opposite walls of the 5 housing 299. The shaft 341 carries a gear 342 meshing with a similar gear 343, and this gear is supported by a shaft 344, also journaled in the opposite side walls of the housing 299. The shaft 344 forms the drive means of a pump for 10 transmitting polishing material from a suitable reservoir, to be described, to the brush 316.

Referring to Figures 23, 24 and 25, the numeral 345 designates an outstanding bracket formed integral with the gear housing 299. This bracket 15 includes a vertical web 346 and respectively relatively wide and narrow lower and upper webs 347 and 348, the bracket being shown in cross-section in Figure 21. This bracket supports an integral pump housing 349, as clearly shown in Figure 25, 20 and recesses 350 and 351 are formed in the outer face of the housing 349 for the reception of pump gears 352 and 353 respectively, the latter being carried by the outer end of the shaft 344. The outer face of the gear housing is closed by a suitable plate 354 secured to the housing by screws or the like 355 (see Figures 23 and 25). The pump housing 349 is provided with an upper inlet passage 356 and a lower outlet passage 357.

A polish reservoir indicated as a whole by the 30 numeral 358 is supported by the bracket 345. This reservoir includes upper and lower telescoping casing sections 359 and 360. The lower section 360 carries a ring 361 at its lower end threaded for reception within a flange 362 carried by and formed integral with the top of the 35 pump housing 349. A plate 363 is threaded within the lower end of the casing section 360 and carries a central depending boss 364 seating against the top of the pump housing 349. The 40 boss 364 is provided with an opening 365 communicating at its upper end with the interior of the casing section 360 and at its lower end with a vertical passage 366, the lower end of the latter passage communicating with the pump inlet passage 356 as shown in Figure 24. The upper face of the plate 363 is provided with a concentric recess 367 for a purpose to be described.

A plunger 368 is arranged within the casing section 360. This plunger includes an upper 50 plate 369 and a lower plate 370 between which is clamped a deformable packing member 371 by screws 372. The upper plate 369 carries a boss 373, and a stem 374 extends through the plate 369 and its boss 373, and through the packing 55 member 371 and lower plate 370. The stem 374 carries a lower head 375 which is slightly smaller than the recess 367 and is arranged therein out of contact with the surfaces thereof under conditions to be described. The upper end of the 60 stem 374 is carried by a head 376 forming a cover for the upper casing section 359. A spring 377 urges the plunger 368 downwardly, and upward movement of this member is limited by a ring 378 secured within the lower casing section 360. 65 The upper casing section 359 is provided with a vertical slot 379 having an offset 380 at its upper end and a similar offset 381 adjacent its lower end. A lug 382 carried by the lower casing section 360 is arranged in the slot 379 and is engagementable in either of the offsets 380 or 381 under conditions to be described.

The bracket 345 carries an enlarged angular cylindrical portion 383 formed integral therewith and angularly arranged as shown in Figure 75 25. The portion 383 is drilled as at 384 to form a

passage communicating at one end with the pump outlet passage 357, and the opposite end of the passage 384 is plugged as at 385. The bracket 345 is likewise provided with an integral vertical cylindrical portion 386 having a vertical 5 passage 387 therethrough communicating at its lower end with the outer end of the passage 384.

At its upper end, the cylindrical extension 386 carries an integral combined guard and polish-applying member 388 (see Figures 9, 10, 13 and 21). The guard 388 is provided with an orifice 389 through which polish is pumped from the upper end of the passage 387 to the polish-applying brush 316. At this point, attention is invited to the fact that two of the polish reservoirs and 15 associated parts are employed, one for use in connection with each polish applying brush 316, as shown in Figure 9. The upper end of the passage 387 may communicate directly with the orifice 389, or a separate casing 390 may be 20 secured against the back of the guard 388 by screws or the like 391. If such separate casing is employed, it will be provided with a lower passage 391 communicating with the upper end of the passage 387, and also an orifice 392 communicating with the orifice 389.

As previously stated, the movement of the polish-applying brushes 316 toward and away from the shoes is controlled initially by the cam 228 (see Figures 8 and 34). During the third and 30 fourth cyclic operations of the traveling brush units, the polish-applying brushes 316 are in engagement with the shoes, as will become apparent, and means are provided for limiting the inward swinging movement of the brushes 316. As 35 shown in Figure 16, the gear housing 299 is provided with an integral arm 393 carrying a roller 394 supported with respect thereto by a stub shaft 395. This roller is engageable with a contour plate 396 formed integral with and arranged beneath each of the foot rests 19. It will become apparent that the polish-applying brushes of the toe units are held in the inoperative position shown in Figure 16 through the positive engagement of the roller 296 with the cam 337, and during the third and fourth cyclic operations of the traveling brush units, the polish-applying brushes are released for inward movement and are urged 45 inwardly by the spring 336 of each traveling brush unit. The roller 394 of each unit obviously 50 limits the inward movement of the polish-applying brushes to prevent them from bearing against the shoe rests 19 when the machine is not occupied.

Means are provided for positively driving the 55 polish-applying brush 316 of each traveling unit and for positively driving the polish supplying pump of each unit when such brushes are released for inward movement into engagement with the shoe. Referring to Figure 13, it will be recalled that the sleeve 303 is constantly driven during the operation of the apparatus, but it will be apparent that the shaft 310 is operated only when the clutch elements 313 and 314 are brought into engagement. The upper clutch element 314 is constantly urged downwardly by the spring 315, but is held in its upper inoperative position during all except the third and fourth cyclic operations of the traveling brush units.

Referring to Figures 14 and 23, the numeral 70 397 designates a lever pivotally supported intermediate its ends as at 398 by the outer wall of each housing 299. One end 399 of the lever 397 is provided with a cam 400 having its high portion 401 normally arranged beneath a roller 402 75

supported by a stub shaft 403 carried by the vertical arm 292'. The other end 403' of the lever 397 is provided with a pin 404 projecting through a vertically elongated opening 405 formed in the adjacent wall of the casing 299 and connected to a fork 406 engaging in an annular groove 407 formed in the upper clutch member 314. A washer 408 surrounds the pin 404 and closes the opening 405, and this washer is maintained against the adjacent wall of the casing 299 by a spring 409 also surrounding the pin 404. It will become apparent that during all except the third and fourth cyclic operations of the traveling brush units, the roller 402 is in engagement with the high point 401 of the cam 400, thus maintaining the lever arm 399 in its lower position, and the lever arm 403' in its upper position, thus holding the clutch element 314 out of engagement with its coacting element 313. Upon the releasing of the casing 299 for inward movement, the roller 402 moves to the low point of the cam 400, thus permitting the spring 315 to urge the clutch element 314 into engagement with the element 313 to transmit positive rotary motion from the sleeve 303 to the shaft 310. Under such conditions, the polish pumps of the traveling brush units will supply polish to the brushes 316 and the latter, during such time, remain in engagement with the shoes to apply polish thereto.

Means are also provided for supplying polish to the polish-applying brushes 150 of the toe brush units. Such means includes the pipes 164 and 165 and the pump and reservoir unit 166 previously described. This unit is arranged at one side of and secured to the main frame of the machine in the position indicated in Figures 4 and 6. This unit, per se, is illustrated in detail in Figures 26 to 31 inclusive. Referring to Figures 26, 27 and 28, the numerals 410 and 411 designate a pair of telescoping casing sections similar to the casing sections 359 and 360 of the polish reservoir for the traveling brush units. One end of the casing 410 is provided with a band 412 threaded in an annular flange 413 of the pump unit to be described. The same end of the casing 410 is provided with a threaded head 414 having an axial opening 415 and an axial recess 416 of substantial size.

A plunger indicated as a whole by the numeral 50 417 is reciprocable in the casing 410. This plunger includes a pair of plates 418 and 419 having a packing member 420 clamped therebetween by suitable screws 421. A stem 422 projects through the plates 418 and 419 and the washer 420, and through an integral boss 423, carried by the plate 418. The adjacent end of the stem 422 is provided with a head 425, as shown in Figure 28.

The casing 411 is provided at its free end with a head 426 through which the adjacent end of the stem 422 is threaded, and a suitable lock nut 427 is threaded on the upper end of the stem. A compression spring 428 has one end engaging against the head 426 and its other end against the plunger 417 to urge the latter toward the pump mechanism, and movement of the plunger in the opposite direction is limited by a band 429 secured within the casing 410. The casing 411 is provided in one side thereof with a longitudinal slot 430 having laterally offset portions 431 and 432, as shown in Figure 26. A lug 433 is carried by the casing 410 and is relatively slidably longitudinally in the slot 430 and is adapted to assume positions within the offsets 431 and 432, for a purpose to be described.

75 The housing of the pump unit associated with

the reservoir just described is preferably formed as an integral casting and is designated as a whole by the numeral 434. This housing is elongated longitudinally with respect to the reservoir as shown in Figures 26, 27 and 28. At opposite sides 5 and at preferably offset points the pump housing is provided with laterally projecting ears 435 having elongated slots 436 therein. These slots receive machine screws or other fastening elements 437 which are threaded into a relatively heavy 10 supporting boss 438 (see Figures 4, 6, 11 and 26) preferably formed integral with the wall 58 of the main frame of the apparatus. It will become apparent that the slots 436 are provided to permit longitudinal adjustment of the pump mechanism to thereby permit adjustment of the rate of supply of polishing material to the toe brush units. The casing 434 is locked in adjusted positions by screws 437' threaded in opposite ends of one of the lugs 435.

Referring to Figure 28 the numeral 439 designates a pair of spaced parallel longitudinal openings drilled through the housing 434 and terminating a short distance from the inner end thereof. A somewhat larger transverse passage 25 440 is drilled laterally through the housing 434 and is plugged at its outer end as at 441. The passage 440 obviously intersects and connects the inner ends of the passages 439, and the passage 440 communicates with the opening 415 30 through a supply passage 442. The adjacent end of the pump housing is provided with a seat 443 against which the central portion of the head 414 seats when the reservoir is assembled with respect to the pump housing. 35

Pump plungers 444 reciprocate in the respective openings 439, as shown in Figure 28. The outer ends of the openings 439 are enlarged to receive suitable packing 445 and such packing is maintained in position by glands 446. A guide 40 plunger 447 is reciprocable in a guide opening 448 formed in the housing 434. The plunger 447 carries a crosshead 448' to which the outer ends of the pump plungers 444 are connected. An arm 449 is formed integral with the crosshead 448' 45 and carries a roller 450 supported with respect thereto by means of a stub shaft 451. The guide plunger 447 is lubricated by a suitable wick 452 maintained in position by a screw 453 mounted in a boss 454 projecting laterally from the housing 434. 50

As previously stated, the first two cyclic operations of the traveling brush units clean the shoes by brushing dust and dirt therefrom, and during such operation polish is supplied to the 55 brushes 150 of the toe brush units. Cam means is provided for actuating the pump plungers 444 for supplying the polish to the brushes 150 through the polish supplying units associated with the toe brush units. The operating cam for 60 the pump plungers 444 is shown in Figures 28 and 37, such cam being shown in starting position as is the case of all of the cams employed for controlling various parts of the apparatus. The cam is designated as a whole by the numeral 455 and includes a cam groove 456 in which the roller 450 travels. A substantial portion of the cam groove 456 is concentric, and all of the operating portion of the cam is located between the two points 457 and 458, the distance between 70 these points representing the first two cyclic operations of the traveling brush units. After the point 458 passes the roller 450, retraction of the pump plungers 444 commences, and these plungers are restored to normal position to be held in 75

such position by the concentric portion of the cam groove 456 until the entire operation of the apparatus has been completed. At such point, the roller 450 will again assume the position 5 shown in Figures 28 and 37 ready for the next operation of the apparatus.

Referring to Figure 28, the numeral 459 designates a passage drilled through each edge portion of the body 434 and communicating with 10 the adjacent ends of the openings 439. The inner ends of the passages 459 communicate with the passage 442 through reduced passages 460, the outer ends of the passages 460 forming seats each engaged by a ball check valve 461. Each of 15 these valves is urged toward closed position by a spring 462, and the outer end of each spring seats within a plug 463. The inner ends of the passages 439, between the passages 440 and 459, communicate with outlet passages 450', through 20 small passages 451' controlled by ball check valves 452'. Each check valve 452' is urged inwardly by a spring 453' having its outer end seating in a cap 454'. The two passages 450' communicate with the respective pipes 164 and 165. These 25 pipes are connected to bosses 464 (see Figures 27 and 30) and the interiors of the bosses 464 communicate with the passages 450' through passages 465.

Means are provided for preventing the operation 30 of the apparatus when one or more of the polish reservoirs becomes empty. Such means need not be provided for all reservoirs since the reservoir for the toe brush units may be made of slightly less relative capacity than the reservoirs for the traveling brush units, in which case 35 the control means may be employed in connection with the toe brush reservoir. A portion of such control means is illustrated in Figures 26 and 27 and the electrical connections for such 40 means will be described later. The housing 434 is provided with a pair of spaced outstanding arms 466 having complementary cut out portions 467 for the reception of an insulating sleeve 468. This sleeve carries a contact 469 having a binding post 470 at one end for connection with a 45 lead wire to be described.

The sleeve 468 is adapted to be clamped between the arms 466 by means of a screw 471. An outstanding lug 472 is carried by the upper 50 end of the housing 434 and supports a plunger 473 for vertical sliding movement. The upper end of this plunger carries a head 474 urged upwardly by a spring 475. The plunger 473 is engageable by a flange 476 carried by the casing 55 411, and the flange 476 is operative, in a manner to be described, when the reservoir within the casing 410 is emptied, for moving the plunger 473 downwardly into engagement with the contact 469. This operation closes a control circuit to 60 return to a prospective user a coin inserted in the coin control mechanism to be described.

The coin control mechanism and electrical circuits for controlling the apparatus are shown in Figure 39, the arrangement of the coin control 65 mechanism with respect to other parts of the apparatus being shown in Figures 2 and 3.

The pedestal 15 houses a coin chute 477 having a flared upper end 478. A coin slide 479 is provided with a coin receiving opening 480 in 70 which a coin is deposited when the slide is in the position shown in Figure 3. When this slide is pushed inwardly it deposits the coin in the upper end 478 of the coin chute, and the disposition of the coin depends upon the conditions 75 present, as will be described. For example, if

the apparatus is in proper operative condition, the coin will drop through the chute 477 and will be deposited in a coin box 481, arranged beneath the top plate 13. This coin box is accessible through a door or plate 482, but may be formed integral with said plate. The plate 482 is provided with a suitable lock 483 (see Figure 2) which may be of any desired type, and the plate 482 is provided with a keyhole 484 to provide access to the lock as shown in Figure 1. 10

Means are provided for returning the coin when the seat 11 is unoccupied, or when the supply of polishing material has become exhausted. Referring to Figures 2 and 39, the numeral 485 designates a branch chute having its lower end arranged over the inner end 486 of a coin return receptacle 487. The receptacle 487 is provided with a flange 488 by means of which it is secured to one wall of the pedestal 15. A coin diverting paddle 489 is arranged within the flared upper 20 end 478 of the main coin chute and is pivotally supported at its lower end as at 490 adjacent the junction between the chutes 477 and 485. When the seat 11 is occupied and the polish reservoirs are still supplied with polishing material, the insertion of a coin results in such coin falling through the chute 477, the paddle 489, under such conditions, occupying the dotted line position shown in Figure 39. If the supply of polishing material is exhausted, or if the coin is inserted 30 before the user occupies the seat 11, the paddle 489 will assume the solid line position shown in Figure 39, in which case an inserted coin will be diverted to the chute 485 and thus will be returned to the user through the receptacle 487. 35

The position of the paddle 489 is controlled by means of a solenoid 491 having an armature 492. The upper end of this armature is connected to a flexible wire 493 and the upper end of this wire is connected as at 494 to one end of a crank 40 495. This crank is connected to the paddle 489, as will be apparent. The use of the wire 493 is suggested as a matter of simplicity, and it will be obvious that any suitable mechanical connection may be employed between the armature 492 45 and the crank 495. The weight of the armature 492 normally holds the paddle 489 in its dotted line position, but the energization of the solenoid 491 in a manner to be described moves the armature 492 upwardly, thus swinging the paddle 489 50 to the solid line position shown in Figure 39.

The seat 11 also is adapted to control the position of the paddle 489 independently of the solenoid 491. As previously stated, the seat 11 is supported above the pedestal 12 and the supporting 55 means for the seat is shown in Figure 39. A rod 496 is connected at its upper end to the seat 11 and extends through the pedestal 12 and into the base of the apparatus. A collar 497 is carried by the rod 496 and is urged upwardly by a spring 60 498. The lower end of this spring seats on a spider 499 arranged within and secured to the pedestal. The collar 497 engages the top of the pedestal to limit the upward movement of the seat 11 and its supporting rod, but the seat is 65 movable downwardly against the tension of the spring 498 when occupied by a person using the apparatus. Downward movement of the seat 11 is limited by the top of the pedestal 12.

The lower end of the rod 496 is pivotally connected as at 500 to a lever 501. This lever has one end supported by a stationary pivot 502, and the other end of the lever is connected as at 503 to the lower end of a vertically extending rod 504. This rod is provided with suitable guides (not 75

shown) and has its upper end arranged beneath and engageable with the lower end of the armature 492. The chair 11, when unoccupied, is arranged in the position shown in Figure 39, in which case the rod 504 holds the armature 492 in its upper position, thus holding the paddle 489 in position to divert coins into the chute 485. Thus it is impossible for the machine to collect and retain a coin inserted when the seat 11 is unoccupied, the coin being returned under such conditions through the chute 485.

A pair of line wires 505 and 506 are connected to a suitable source of current, ordinarily a 110 volt source, as will be apparent. The wire 505 is connected to a contact 507 which is engageable, in turn, by a contact 508 depressible by the rod 496 when the seat 11 is occupied. The contact 508 is connected to one end of a wire 509, and the other end of this wire leads to a conventional magnet operated switch 510. From the switch 510, a wire 511 leads to one terminal of the motor 26. The other terminal of this motor is connected by a wire 512 to the line wire 506. When the magnet operated switch is actuated in a manner to be described, the wires 509 and 511 are connected to each other, and the motor 26 will be energized, the seat 11 under such conditions being occupied to close the circuit between the contacts 507 and 508.

30 A shunt circuit is provided to permit the motor 26 to be operated at will independently of the coin control mechanism and associated elements, for the purpose of inspection and repair. This shunt circuit includes a wire 513 leading to a joggle switch 514, and a wire 515 leads from the joggle switch to the wire 511. It will be apparent that the switch 514 may be closed independently of the position of the seat 11 and without the insertion of a coin in the coin receiving mechanism 40 to close a circuit through the motor 26, and this circuit will remain closed as long as the switch 514 is closed.

A transformer 516 has the terminals of its primary coil 517 connected by wires 518 and 519 to the respective wires 506 and 509. Energization of the transformer primary 517 is thus dependent on the seat 11 being occupied, and the operation of the motor 26 is dependent upon the insertion of a coin into the coin receiving mechanism. The transformer includes a secondary 520 having its terminals connected to wires 521 and 522. Two wires 523 and 524 lead into the magnet operated switch 510 to energize the magnet thereof under proper conditions, and the wire 523 is tapped into the wire 522. Energization of the magnet operated switch connects the wires 509 and 511 to each other. As will become apparent, the apparatus then completes its entire operation, whereupon the pin 86, carried by the cam 70 engages the arm 525 to move it upwardly, and then release it for downward movement to break the circuit between the wires 509 and 511 between the next operation of the apparatus.

The wire 521 leading from the transformer secondary is connected to a contact 526 engageable by a switch arm 527. This switch arm is connected to an actuating arm 528 arranged in the path of travel of coins dropping through the chute 477, the passage of a coin through this chute momentarily closing a circuit between the contact 526 and switch 527. The switch 527 is connected to the other end of the wire 524 leading to the magnet operated switch.

The terminals of the solenoid 491 are connected 75 by wires 529 and 530 to the terminals of a sig-

nal 531 which may be in any suitable form such as a light or bell. A wire 532 has one end tapped into the wire 521 and its other end connected to the wire 530. The wire 529 is connected by a wire 533 to the contact 473 associated with the polish reservoir for the toe brush units (see Figure 26). As previously stated, such contact is movable into engagement with the contact 469, and the latter contact is connected to the wire 522. It will be apparent that the circuit of the magnet switch 510 is completed from the transformer secondary 520 merely upon the actuation of the arm 528 incident to the introduction of a coin into the chute 477. The solenoid 491 and signal 531 are connected in parallel to be simultaneously energized, but such energization occurs only through the closing of the circuit across the contacts 469 and 473 and this action occurs only when the reservoir for the toe brush units is empty.

The operation of the apparatus is as follows: 20

As previously stated, the traveling units and toe brush units normally occupy the positions shown in Figure 1, the brushes of the traveling units being arranged adjacent the forward ends 25 of the shoes while the brushes of the toe polishing units are elevated. The elevation of the toe brush units is controlled by the cams 167 and 178, and these cams have been shown in Figures 35 and 36 as being in their starting positions. It will become apparent that the cam 167 rotates 30 once for each cyclic operation of the traveling brush units while the interference cam 178 makes one complete revolution during the entire operation of the apparatus. The cam 178 is of such length as to maintain the toe brush units elevated 35 during the first two cyclic operations of the apparatus during which time the brushes 322 of the traveling units brush the shoes to remove dust and dirt therefrom. The various cyclic operations of the apparatus can be clearly followed if it is borne in mind that the various elements in Figures 32 to 37 inclusive are arranged in their starting 40 positions. The cyclic operations of the apparatus are also diagrammatically represented in Figure 40 of the drawings. 45

When a customer desires to use the apparatus, he first takes his position on the seat 11 and places his feet upon the foot rests 19, whereupon it is merely necessary to insert the proper coin in the opening 480 (see Figure 3) of the coin slide 479, and to push the slide inwardly. This action takes place with the chair supporting rod 496 and the lever 501 moved downwardly, and accordingly the paddle 489 will be in the dotted line position shown in Figure 39. Under such conditions, the coin will drop through the coin chute 477 to close the switch 527 by contact with the arm 528, whereupon the apparatus starts its operation and completely polishes the shoes before coming to an automatic stop with all of the parts restored to the normal position previously described. 55

Assuming that a prospective user should insert a coin in the coin chute before taking his position on the seat 11, the rod 496 and lever 501 will be 60 in their upper positions and the coin paddle 489 will be in its normal or solid line position shown in Figure 39. Under such conditions, the coin will be returned through the chute 485. Assuming that a prospective user properly takes his position on the seat 11 and inserts a coin into the apparatus, the coin will be returned if the polish reservoir of the toe polishing units should be empty. Under such conditions the contacts 469 and 473 will be in stationary engagement with each other, which operation will be referred to in 70 75.

detail later. Under the latter conditions, the depression of the seat 11 incident to the customer taking his position thereon causes the contact 508 to engage the contact 507. Current will then flow, for example, from line wire 505 through contacts 507 and 508, through wires 509 and 519, through the transformer primary 517 and thence back to the source through wires 518 and 506. A circuit through the transformer secondary will be completed under such conditions due to the engagement of the contacts 469 and 473, current flowing through wires 521 and 530, through the solenoid 491 and signal 531, through wires 529 and 533 and contacts 473 and 469, and thence back to the transformer secondary through wire 522.

The signal 531 will be immediately operated to advise the user that the machine is out of operation, and the solenoid 491 will be energized to effect the returning of the coin to the user in the event he should disregard the signal and insert a coin into the apparatus. In this connection it is pointed out that when the user takes his position on the seat 11, his weight depresses rod 496, lever 501 and rod 504, thus releasing the armature 492 for downward movement. This operation thus ordinarily would move the coin paddle 489 to the dotted line operative position, but the energization of the solenoid 491 in the manner described causes the armature 492 to be held upwardly, thus holding the coin paddle 489 in its solid line position. If a user under such conditions should ignore the operation of the signal 531 and insert a coin in the apparatus, such coin will be returned through the chute 485. Since the operation of the motor 26 is dependent upon the closing of the switch 527 in a manner to be described, the apparatus will not be operated under the conditions described.

Assuming that all of the reservoirs are supplied with polishing material and that the user takes his position on the seat 11 and inserts a coin into the coin chute, the operation of the apparatus will be initiated and its operation will be continued until the shoes have been polished and the apparatus is brought to a stop automatically at the end of its complete operation. Under such conditions, the contacts 469 and 473, associated with the polish reservoir of the toe brush units, will be separated and the signal 531 and solenoid 491 cannot be energized. The depression of the seat 11, of course, will have moved the contact 508 into engagement with the contact 507, thus closing the circuit from the source through the transformer primary in the manner previously described. The insertion of the coin then takes place with the paddle 489 in the dotted line position shown in Figure 39, and the coin drops through the chute 477 to be collected in the coin box 481. During its passage through the chute 477, the coin trips the arm 528 to move the switch 527 momentarily into engagement with the contact 526, whereupon the motor 26 will be started.

Upon the closing of the switch 527 a circuit through the secondary 520 will be closed through wire 521, contact 526, switch 527, and wire 524, through the magnet of the magnet operated switch, and thence back to the transformer secondary through wires 523 and 522. In this connection, it is pointed out that the specific structure of a magnet operated switch is of no importance, and any conventional type of magnet operated switch may be employed. The energiza-

tion of the magnet of this switch closes a circuit between wires 509 and 511. This circuit remains closed, regardless of the position of the switch 527, until the machine has completed its various operations. At such time, the finger 86, 5 carried as a matter of convenience by the cam 70, will have moved the arm 525 upwardly and then released it to thus restore the normal condition of the magnet switch 510 and break the circuit through the motor 26 until the next operation of the apparatus. When the wires 509 and 511 are electrically connected by the magnet operated switch, in the manner just described, current flows through line wire 505, contacts 507 and 508, through wires 509 and 511, and 15 thence through the motor 26 and back to the source through wires 512 and 506.

Referring to Figures 4, 5 and 7, it will be noted that operation of the motor 26 drives the shaft 28 through the coupling 27, and the worm 31, 20 carried by the shaft 28, drives the worm wheel 32 and shaft 33. The latter shaft is the main drive shaft of the apparatus and extends longitudinally throughout the length of the main casting as shown in Figure 7. As previously stated, 25 the motor continues in operation until the various operations of the apparatus have all been completed, and during such entire time, the toe brush units will be oscillated on their vertical axes regardless of the vertical or horizontal position of the toe brush units.

Referring to Figures 6 and 7, it will be noted that the main drive shaft 33 carries the crank 111 to which the link 110 is connected. This link is connected at 109 to the lower end 108 of 35 the lever 104, and accordingly it will be apparent that rotation of the shaft 33 oscillates the lever 104 about its pivot 105 throughout the entire operation of the apparatus. The oscillation of the upper end 117 of the lever 104 is transmitted to 40 the rack bar 113 through the link 115, thus causing the rack bar to continuously reciprocate. The teeth of the rack bar mesh with the teeth of the pinion 126 which is rigidly connected to the pinion 125, and since the latter pinion is in constant mesh with the elongated pinion 157, it will be apparent that the sleeve 155 will be continuously oscillated. The sleeve 155 is vertically movable with the toe brush units, and the pinion 157 is elongated to permit the oscillatory movement 50 thereof to continue regardless of the vertical position of the toe brush units.

The sleeve 155 carries the pinion 156 at its upper end, and this pinion meshes with the segment gear 154 of the toe brush unit 147. The 55 oscillatory movement referred to accordingly is transmitted to this toe brush unit to maintain it in oscillation throughout the operation of the apparatus. The toe brush unit 147 also carries the gear 158 (see Figures 9 and 10) and this gear 60 forms the first gear of the gear train including the successively meshing gears 159, 160 and 161. The latter gear is carried by the toe brush unit 148 and obviously this unit is oscillated simultaneously with the unit 147, its oscillations being 65 opposed to the oscillations of the toe brush unit 147 by means of the reversal of motion accomplished through the gears 159 and 160.

As previously stated, the vertical positions of the toe brush units are governed by the cams 167 70 and 178, and the horizontal positions of these units are governed by the cam 70. The toe brush units are shown in their elevated starting positions in Figure 6 of the drawings, the polish-applying brush 150 of each of these units being 75

shown in position over its associated polish-applying device 162. During the first two cyclic operations of the traveling brush unit, the interference cam 178 is in engagement with the roller 181 thus holding the lever arm 171 depressed and elevating the lever arm 173. This lever arm is connected to the crosshead 130 by the links 175 (see Figure 7) and the bosses 131 of the crosshead 130 supporting the rods 127 and 128 by which the toe brush units are supported. Thus these units, together with their polish supplying devices 162, are held in upper position during the first two cyclic operations of the apparatus, each unit oscillating with its polish-applying brush 150 traveling across the face of the plate 162' (see Figure 22) and during such cycles of operation, polish is pumped through the orifice 163 of each toe brush supplying device 162 to supply polish to the brushes 150.

Referring to Figures 4, 6 and 32, the means for horizontally positioning the toe brush units are illustrated. The roller 74 is located in the cam groove portion 76 when the machine is started and remains in such position during the first two cyclic operations of the apparatus. The bar 75 to which the roller 74 is connected thus determines the path of oscillation of the toe brush units with the brushes 150 thereof in position over the polish supplying devices 162. With the roller 74 in the position referred to during the first two cyclic operations of the apparatus, the bar 75 will be held in its rearmost position, thus holding the bell crank lever arm 91 in its rearmost position as viewed in Figure 4. The other bell crank lever arm 95 carries the roller 99 which engages in the recess 103 as shown in Figure 6. Thus the crosshead 130 is held at its limit of movement toward the right as viewed in Figure 6. It will be noted that the stub shaft 105 which pivotally supports the lever 104 is carried by the crosshead 130 and when the latter is held in the position referred to the lever 104 will be held bodily shifted toward the right and will similarly shift the rack bar 113. The position of the rack bar 113 effects the position of the pinions 125 and 126, and the former determines the position of the toe brush units through the medium of the elongated pinion 151 and sleeve 155.

The pumping mechanism 166 is operated during the first two cyclic operations of the traveling brushes and accordingly during these two operations polish will be discharged through the orifices 163 to be picked up by the brushes 150 oscillating thereover. The operation of the pump unit referred to is accomplished through the medium of the cam 455, shown in Figures 28 and 37. The pump operating roller 450 is shown in its starting position in Figures 28 and 37, and the cam 455 rotates in the direction of the arrow. The cam 455 accordingly operates the roller to actuate the crosshead 448 during the first two cyclic operations of the traveling brushes, and it is during this period that polishing material is pumped by the plungers 444 to be discharged to the orifices 163.

In connection with the cam 455 it will be noted that this element operates to move the pump plungers 444 positively in both directions. Referring to Figure 28, and assuming that the apparatus has been previously operated, the roller 450 will have moved past the high point 458 of its operating cam, and will have been thus moved downwardly into the concentric portion of the cam groove. When the roller 450 is at the high point 458 of the cam, the pump plungers 444 are

arranged with their free ends in the ends of the openings 439 adjacent the ports 459, that is, inwardly of the transverse passage 440. The movement of the roller 450 past the high point of the cam and then into the concentric portion of the cam groove 456 will have moved the pump plungers 444 back to the positions shown in Figure 28, and a partial vacuum will have been created within the inner ends of the passages 439. Under such conditions, the pressure of the reservoir spring 428 will have moved the plunger 417 to assist in feeding polishing material from the reservoir casing 410 through the openings 415 and 442. This action unseats the ball valves 461, thus causing the polishing material to flow into the passages 439 and 459. As the inner ends of the plungers 444 enter the transverse passage 440, this passage also will receive the polishing material.

Under the conditions referred to, it will be apparent that the apparatus is ready for the initial operations previously referred to, it being understood that the passages 440 and 442, the inner ends of the passages 439 and the passages 459 will be filled with polishing material. During the first two cyclic operations of the traveling brush units the polish applying brushes 150 of the toe brush units will be oscillating over and in engagement with the polish supplying devices 162, and during such cyclic operations, the cam 455 will rotate in such a manner that the roller 450 will travel relatively from the position shown in Figure 28 to a position in engagement with the high point 458 of the cam. During such period, the roller 450 will be moved inwardly toward the pumping apparatus, and this movement will be transmitted through the crosshead 448 to the pump plungers 444.

As the pump plungers 444 move inwardly their inner ends displace polishing material from the inner ends of the passages 439, and thus through the passages 451, the inward movement of the pump plungers creating a pressure in the passages referred to as soon as they clear the transverse passage 440. During this time of course it will be apparent that the pressure thus created will hold the ball valves 461 on their seats to prevent the return of polishing material to the reservoir, and will unseat the valves 452 whereby polishing material will be discharged through the passages 450' and 455 (see Figure 30) to the pipes 164 and 165 leading to the respective polish supplying devices 162. Accordingly it will be apparent that during the first two cyclic operations referred to the polish-applying brushes 150 will move over the faces of the polish supplying devices 162 in an oscillating movement and will continuously receive polishing material discharged through each orifice 163. The oscillatory movement of the brushes 150 causes the polish to be distributed over the faces of these brushes, and the curved face 162' of each polish supplying device releases the pressure of the bristles against the polish supplying device progressively at the end of each oscillatory movement, thus preventing the polish from being flicked from the brushes. At the end of the cyclic operations referred to, the toe brush units are ready to be lowered and moved bodily to bring the brushes 150 into engagement with the toe portions of the shoes and this operation will be later referred to in detail.

At this point the distribution of power from the main drive shaft 33 may be recalled. The shaft 33 carries the worm 40 meshing with and

driving the worm wheel 41 mounted on the transverse shaft 42. Accordingly it will be apparent that this shaft is constantly operated, and since the pinion 46, Geneva gear driving arm 62 and cam 167 are carried by the shaft 42, these elements also will be constantly operated. The pinion 46 meshes with the gear 47, as shown in Figures 4 and 12. The gear 47 is formed integral with the gear 48 by means of the hub 49, and these elements are freely rotatable on the shaft 50. Accordingly it will be apparent that the pinion 48 rotates with the gear 47, independently of the shaft 50, and this pinion 48 meshes with the gear 54 to drive the shaft 55. The latter shaft 15 accordingly is constantly driven, but through the gear train referred to, its speed of rotation is reduced to the proper ratio to cause it to make exactly one revolution during the fourteen complete cyclic operations of the traveling brush units to be later referred to in detail.

The shaft 55 carries the interference cam 178 (see Figures 4, 5, 11 and 36) and as previously stated, this cam is effective during the first two cyclic operations for holding the toe brush units in elevated position. After the first two cyclic operations the position of the lever arm 171, and hence the vertical position of the toe brush units will be wholly controlled by the cam 167, which is mounted on the shaft 42, and this shaft rotates once for each cyclic operation of the apparatus. Accordingly it will be apparent that once during each cyclic operation the high portion 168 of the cam 167 will depress the lever arm 171 to elevate the toe brush units, and this action takes place while the traveling brush units are moving around the forward ends of the shoes, thus preventing interference between the toe brush units and the traveling units.

The shaft 55 also carries the cam 228, as shown in Figures 4, 8, 11 and 34, and this cam controls the position of the lever arm 231 through the roller 230. The arm 231 is operative by the cam 228 to rock the shaft 233, and this shaft carries the lever arms 235 which are connected to the lower ends of the spindles 213. These spindles operate in a manner to be described to control the application of polish to the shoes by the polish-applying brushes 316 in a manner to be described.

The shaft 55 likewise carries the cam 455 which actuates the pump mechanism with the toe brush units previously described. The Geneva gear controls the transmission of power between the shaft 42 and the shaft 50, on which the pinion 48 and gear 47 are freely mounted. The constant rotation of the shaft 42 rotates the Geneva gear arm 64 once during each rotation of the shaft 42, and consequently once during each cyclic operation of the traveling brush units. At each rotation of the arm 64, the star wheel 59 will be advanced one step, the cut out portion 63 of the hub or disk 62 being opposite the star wheel during such movement. During the remaining rotation of the shaft 42, the concentric portion of the disk 62 engages the end of one of the arms of the star wheel 59 to lock the latter against movement in accordance with the conventional operation of a Geneva gear unit.

Accordingly it will be apparent that the shaft 70 68 is advanced by a step by step movement, each advance occurring once for each cyclic operation of the apparatus. Fourteen such cyclic operations take place in the embodiment of the invention illustrated, and since the star wheel 59 includes seven arms, it will be apparent that this

wheel is rotated twice during each complete operation of the apparatus. The star wheel 59 is connected to the pinion 67 by the hub 68, and the pinion 67 meshes with the gear 69, as shown in Figure 11. The gear 69 is secured to the shaft 50, and since the pinion 67, and gear 69 bear a one to two ratio, it will be obvious that the gear 69 will be rotated once during the complete operation of the apparatus. The same is true of the cam wheel 70, which is carried by the shaft 50, and this cam wheel controls the bodily movement of the toe brush units to determine the position of the brushes 150, 151 and 152 with respect to the toe portions of the shoes. As will be described in detail later, these brush elements of the toe brush units are successively brought into engagement with the shoe after the polishing material has been applied to the brushes 150, to successively apply polish to the toe brush portions of the shoes, polish such portions with the brushes 151 and then buff them with the buffing brush 152.

The traveling brush units are caused to travel in orbital paths around the respective shoes, and this operation, together with the correlated operations of the toe brush units will now be described in detail. As shown in Figures 7 and 10, the main drive shaft 33 carries the worm 186 within the housing 185. This worm meshes with the worm wheel 188 to drive the vertical shaft 189 and the pinion 193 carried by the upper end of the shaft 189 meshes with the large gear 210. Accordingly the gears 210 will be constantly rotated in the same direction and operate to cause the traveling units to move bodily around their respective orbital paths. Each rotation of each gear 210 causes its associated traveling brush unit to make one complete cyclic operation around its orbital path.

Referring to Figure 13, it will be noted that each housing 211 has its bearing portion 241 secured to one of the gears 210. Since both traveling brush units are identical, the operation of only one need be referred to in detail. Since the housing 211 is rigidly connected to the gear 210, as described, it will be apparent that the former moves bodily with the latter, and thus obviously causes the vertical shaft 248 to move in a circular path concentric with the axis of the sleeve 197. The vertical shaft 261 is arranged at a fixed distance from the shaft 248 by virtue of its connection therewith by the carrier 252, but this carrier is adapted to swing about the axis of the shaft 248, through the medium of the bearings 254, and accordingly the shaft 261 is adapted to assume positions at varying distances from the axis of the gear 210. It is this action which permits the shaft 261 to follow around the orbital path defined by the trackway 266 while being positively moved through such path by rotation of the gear 210.

At this point, it may be noted that the two arms 279 and 288 swivel with respect to the shaft 261 and accordingly their respective rollers 281 and 287 are free to follow the trackway 266. The arm 288 is connected to the adjacent plate 274, while the plate 274 at the opposite end of the chain of plates is free from the traveling brush unit as shown in Figure 14. The traveling brush units travel toward the left from the position shown in Figure 14, and accordingly the arm 288 acts to pull the chain of plates 274. This pull is transmitted throughout the chain of plates and their rollers 276 guide the ends of the plates in the trackway 266. One end of the chain of plates is free from the traveling brush unit to insure against any binding action between the rollers 75

276 and the trackway. The plates 274, as clearly shown in Figure 16, serve to completely cover the trackway.

Referring to Figure 10, it will be noted that 5 the gear 195 is secured to the vertical shaft 189 to be driven thereby. The gear 195 meshes with the gears 261 and both of these gears accordingly are constantly driven in the same direction and at a higher speed than the gears 210. The gears 201 10 operate to drive the brushes of the traveling brush units in the manner illustrated in Figure 13. In connection with the latter figure attention is again invited to the fact that the parts of the apparatus are illustrated in such figure with the axes of the 15 sleeves 197 and shafts 248 and 261 arranged in a common plane for the purpose of illustration whereby the various driving means may be clearly followed, but in actual practice, the elements do not assume such position, since swinging movement of the shaft 261 away from the axis of the sleeve 197 is limited by the trackway 266.

Rotation of the pinion 201 of each traveling brush unit rotates the sleeve 199 connected thereto. This rotational movement is transmitted to 20 the collar 205 to rotate the bevel gear 206 and thus drive the bevel gear 244. The latter pinion is carried at one end of the shaft 243 and the other end of this shaft carries the pinion 245, and accordingly it will be apparent that such pinion 25 rotates to drive the bevel gears 250 and 251. The latter gear meshes with and drives the bevel pinion 258, carried by the shaft 257, and the pinion 262 accordingly is rotated to drive the bevel pinion 263. Thus it will be apparent that the shaft 30 261 will be constantly driven, and since the shaft 257 and its pinions 258 and 262 are supported by the carrier 252, it will be apparent that this carrier and the shaft 261 are free to swing with respect to the axis of the shaft 248 without disturbing the meshing engagement of the several 35 gears 251, 258, 262 and 263.

The gear 309 is fixed to the shaft 261 to be rotated therewith, and constantly meshes with the gear 327 carried by the vertical shaft 321. 40 This shaft is supported by the arms 319 and 320 which swing concentric with the axis of the shaft 261 and accordingly the gears 309 and 327 remain in mesh as the arms 319 and 320 swing with respect to the shaft 261 incident to movement of the unit around its orbital path. Thus it will be 45 apparent that the brush 322 is constantly driven, and its torsion spring 331 operates to maintain the brush 322 in engagement with the shoe under all conditions throughout the complete operation of the apparatus. It will become apparent that during the first two cyclic operations of 50 the traveling brush unit, no polish is applied to the brush 316 and this brush remains out of engagement with the shoe, and during such period 55 the brush 322 operates to clean dust and dirt from the shoe.

As previously stated, the torsion spring 331 urges the brush 322 toward the shoe. The inner end of the spring 331 is connected to the sleeve 60 328, while the outer end 332 of the spring bears against the edge of the housing member 317 as shown in Figures 13 and 14. In a similar manner, the spring 336 urges the housing 299 inwardly together with the polish-applying brush 316. The inner end of the spring 336 is connected to the sleeve 333 while the outer end of the spring 65 operates against the spring seat 337, as shown in Figure 14. The spring sleeves 328 and 333 are relatively rotatable with respect to each other. These sleeves are provided with the 70 75

lower annular flanges 329 and 334, and these flanges are provided with the respective openings 330 and 335. The springs are tensioned by inserting suitable members in the openings 330 and 335 and rotating the associated spring sleeves, 5 whereupon pins 335' are inserted through the openings 335' in the connecting wall 292', and the inner ends of these pins are inserted into one of each of the openings 330 and 335. Thus the spring sleeves are prevented from rotating with respect 10 to the connecting wall 292' and the springs operate to exert a constant inward tension on the housings 299 and 317, in the manner previously stated.

The sleeve 303 in the housing 299 is driven by 15 the means disclosed in Figures 13 and 15. The gear 309 which drives the gear 327 also meshes with the pinion 308. The pinion 307 meshes with the pinion 308 and with the gear 304 carried by the sleeve 303. Thus the sleeve 303 is constantly 20 driven during the entire operation of the apparatus, but it does not drive the brush 316 or operate the polish pump means for the traveling brush units except during the third and fourth cyclic operations of the apparatus. The function of 25 driving the brush 316 and operating the polish-applying means is controlled by the cam 228 (see Figures 4 and 34) as previously described.

Referring to Figure 34, it will be noted that the roller 230 is shown in its position at the beginning 30 of the operation of the apparatus. Accordingly, with the cam rotating in the direction indicated by the arrow, the arm 231 will remain in its initial position during the first two cycles of the 35 operation of the apparatus, but during the third and fourth operations, the roller 230 will occupy positions corresponding to the points 239 and 240, the connected low points of the cam 228. As previously stated, the polishing brush 322 cleans the 40 shoes during the first two cyclic operations of the apparatus, and when the roller 230 occupies the operative position referred to adjacent the points 239 and 240, automatic means will come into 45 operation to release the polish-applying brush 316 for movement into engagement with the shoe, and polish will be supplied thereto to be transferred to the shoe.

Referring to Figures 4, 8 and 10, it will be noted that the lever arms 235 and 237 are connected at one end to the shaft 233 and at their other ends 50 to the spindles 213. When the roller 230 moves into the cam positions 239 and 240, the lever arm 231 swings upwardly, thus moving the lever arms 235 and 237 downwardly together with the spindles 213. The operation resulting from the downward 55 movement of each spindle 213 is identical, and only one need be described. As shown in Figures 8, 10, 13 and 20, each spindle 213 carries the transverse pin 215 adjacent its upper end, and downward movement of this pin with respect to the 60 sleeve 197 is permitted by the provision of the slots 214. The pin 215 transmits vertical movement to the crosshead 217, thus similarly moving the housing 222 and rod 224 vertically. The latter rod is connected at its end as at 298 to the 65 yoke 297 of the sleeve 293, and thus it will be apparent that downward movement of the spindle 213 effects downward movement of the sleeve 293.

The sleeve 293 is vertically slidable on the square shaft 291 and accordingly is fixed against rotation with respect thereto while being free to partake of vertical movement. Since the position of the arms 290 and 292 is determined by engagement of the roller 287 in the trackway 266 (see Figures 13, 15 and 16) it will be apparent that the 70 75

5 arms 290 and 292 always project laterally inwardly from the trackway 288. Accordingly, the roller 296, carried by the sleeve 293, is always arranged in proper position to cooperate with the cam 337. 10 This roller engages the cam edge 338 of the cam member 337, and when the spindle 213 is in its uppermost position, the engagement of the roller 296 against the cam edge 338 holds the housing 299 and associated parts turned to its outer position, 15 as shown in Figure 16.

10 As previously stated, the roller 402, carried by the connecting member 292', occupies a position over the high point 401 of the cam 400 (see Figure 23) when the housing 299 is swung outwardly. 15 When the roller 230 moves into the cam portion 239, the spindle 213 will be pulled downwardly, as previously stated, and the roller 296 will move downwardly along the cam edge 338, thus permitting the torsion spring 336 to swing the housing 299 inwardly. This condition is reached at the 20 third cyclic operation of the apparatus and continues through the fourth cyclic operation and accordingly the polish-applying brush 316 will remain in engagement with the shoe during such 25 third and fourth cyclic operations.

The inward swinging of the housing 299 not only moves the polish-applying brush 316 into engagement with the shoe, but also automatically starts the operation of the means for supplying 30 polish to the brush 316. When the housing 299 swings inwardly, the lever 397 swings bodily therewith, being pivotally connected to the housing 299 as at 398. Thus the cam high point 401 moves from its position beneath the roller 402, and the 35 lever arm 399 moves upwardly. The lever arm 403' obviously moves downwardly and this action is effected by means of the spring 315 (see Figure 13) operating against the upper clutch element 314. In this connection, it will be recalled that 40 the pin 404 projects through the elongated opening 405 and carries the fork 406 at its inner end, engaging in the groove 407 of the upper clutch member 314. Thus, when the high cam point 401 passes from beneath the roller 402, the clutch 45 spring 315 effects downward movement of the upper clutch element 314, thus bringing this element into operative engagement with the clutch element 313.

Under such conditions, the shaft 310 will be 50 locked to the sleeve 303 to be positively driven therewith, and accordingly the brush 316 will start to rotate in engagement with the shoe. At the same time, polish will be supplied to this brush by means of the pump mechanism and reservoir 55 means illustrated in Figures 23, 24 and 25. Rotation of the brush shaft 310 drives the pump shaft 344 through the worm 339, worm wheel 340, and gears 342 and 343. Thus the pump gears 352 and 353 will start to operate simultaneously with the 60 operation of the polish-applying brush 316.

The pump gears 352 and 353 withdraw polishing material from the reservoir casing 360 (see Figure 24) through the opening 365 and passages 366 and 356, the partial vacuum created by 65 the pump gears permitting the spring 377 to urge the plunger 368 downwardly. The pump discharges the polishing material through the successive passages 357, 384 and 387, and from the upper end of this passage, the polishing material is discharged through the orifice 389. This orifice may be covered with a suitable screen, as 70 shown in Figure 21, and is formed in the guard 388. The central portion of the guard 388 contacts with the polish-applying brush 316, and 75 accordingly it will be apparent that polish will be

supplied to this brush during the operation of the pump gears 352 and 353. From the foregoing description it will be apparent that during the third and fourth cyclic operations of the apparatus, the roller 230 will occupy the positions 239 and 5 240 of the cam 228, thus lowering the spindles 213 to automatically accomplish the function of swinging the brush 316 into engagement with the shoe, positively driving this brush, and positively operating the polish pump to supply polish to 10 the brush 316.

At the end of the fourth cyclic operation, the roller 230 moves to the outer or concentric portion of the cam groove 229, thus swinging the roller 230 downwardly and elevating the spindles 15 213. This operation effects upward movement of the sleeve 293 through the means previously described, and the roller 296 again engages the cam edge 338 to swing the housing 299 outwardly. This operation disengages the brush 316 from the 20 shoe and simultaneously stops the operation of the brush and of the pump gears 352 and 353. The outward swinging movement of the housing 299 causes the lever cam 401 to pass beneath the roller 402 to be depressed thereby. Thus the 25 upper clutch element 314 will be released from engagement with the lower clutch element 313, thus restoring the normal condition of the polish applying brush unit. In other words, rotation of the shaft 310 will stop, thus rendering the 30 brush 316 inoperative and stopping the operation of the pump gears 352 and 353. In connection with the operations just described, attention is invited to the fact that the bar 224 is fixed against vertical movement with respect to the 35 guide 222, and accordingly transmits vertical movement to the sleeve 293 upon actuation of the spindle 213. However, the bar 224 is freely slideable horizontally, thus compensating for varying 40 distances between the pivot pin 298 and the axis of the spindle 213 incident to the radial movement of the traveling brush unit.

During the remaining cyclic operations of the apparatus, the roller 230 will remain in the concentric portion of the cam groove 229, and the 45 polish-applying means of each traveling brush unit will remain inoperative. As previously stated, the first two cyclic operations are occupied with the brushing of dust and dirt from the sides of the shoes while polish is being applied 50 to the brushes 150 of the toe brush units, while during the third and fourth cyclic operations, polish is applied to the sides of the shoes by the 55 brushes 316. The present apparatus is designed to perform fourteen cyclic operations and accordingly the remaining ten operations are occupied by the successive movements of the polishing brushes 322 around their orbital paths to impart a proper polish to the side portions of the shoes. 60

During the first two cyclic operations of the apparatus, the toe brush units are held in elevated position with the brushes 150 thereof over the respective polish supplying devices 162, and the brushes oscillate while polish is pumped to the 65 brushes 150. This operation was previously described in detail, and is followed by the automatic operation of lowering the toe brush units and the bodily swing of these units to bring the brush members 150 into engagement with the toe 70 portions of the shoes to apply polish thereto. The bodily movement of the toe brush unit is controlled by the cam 70 (see Figures 4 and 32) while the vertical position of the toe brush units is determined during the first two cyclic operations 75

by the interference cam 178 and thereafter by the cam 167 illustrated in Figures 5 and 35.

At the beginning of the operation of the apparatus, the roller 74 is arranged in the concentric portion 76 of the groove of the cam 70 as shown in Figure 32. It remains in this position during the first two cyclic operations of the traveling brush units, and as previously described, the application of polish to the brushes 150 takes place 10 during this period. The cam 70 rotates in the direction of the arrow in Figure 32, and after the completion of the second cycle of operation the roller 74 moves into the lowermost portion 81 of the cam groove for the third cycle of operation and into the portion 82 during the fourth cycle, the roller 74 being maintained in the same position in the cam groove portions 81 and 82. At the completion of the second cycle of operation, therefore, the roller 74 and its rod 75 will 20 be moved to its innermost limit of movement with respect to the axis of rotation of the cam 70. Thus the bell crank lever arm 91 will swing to the right as viewed in Figure 4 to its limit of movement, thus swinging the arm 95 to move the 25 crosshead 100 to its limit of movement toward the left as viewed in Figure 6.

This movement shifts the lever 104 bodily through the medium of its supporting shaft 105, thus shifting the rack bar 113 toward the left as 30 viewed in Figure 6. This movement is transmitted to pinions 126, 125 and 157, sleeve 155, pinion 156 and segment gear 154 to the toe brush unit 147, and this movement is transmitted to the toe brush unit 148 through gears 158, 159, 160 and 35 161. Under such conditions, the toe brush units will swing substantially to the dotted line positions shown in Figure 9 with the brushes 150 arranged directly above the toe portions of the shoes. This action occurs, as stated, at the completion 40 of the second cycle of operation, and at the same time, the interference cam 178 will pass from the roller 181, thus permitting the lever arm 171 to move upwardly. Thus the supporting means for the toe brush units will be lowered to 45 bring the brushes 150 into contact with the shoe. As previously stated, the toe brush units are constantly oscillated throughout the operation of the apparatus, and accordingly the brushes 150 oscillate in contact with the shoes during the third 50 and fourth cyclic operations to apply polish to the toe portions thereof.

The toe brush units are maintained elevated continuously during the first two cycles of operation, and during the third and fourth cycles, 55 the toe brush units are lowered to permit the brushes 150 to apply polish to the toe portions of the shoes. At the same time, namely, during the third and fourth cycles of operation, the traveling brush units are moving in their orbital paths around the shoe while polish is applied to the brushes. To prevent interference between the toe brush and traveling units, the cam 167 is provided. The cam 167 rotates once during each cyclic operation, and as the traveling units brush the toe portions of the shoes, the high concentric portion 168 of the cam 167 depresses the roller 172 and lever arm 171, thus moving the crosshead 130 upwardly to elevate the toe brush units. The cam portion 168 is of 60 the proper length to hold the toe brush units elevated until each traveling unit has passed completely around the forward end of the corresponding shoe, whereupon the roller 172 passes from beneath the cam portion 168 to again drop 75 the toe brush units to operative position. Thus

it will be apparent that polish is not transferred from the brushes 150 to the toe portions of the shoes throughout the third and fourth cyclic operations, but only during those portions of such cycles of operation during which the traveling brush units are at the sides and back of the shoe. Thus it will be apparent that the toe brush units are prevented from interfering with the orbital movement of the traveling brush units, and during all of the remaining functions 10 of the toe brush units, the same operation takes place, since the cam portion 168 operates to elevate the toe brush units from the third to the fourteenth cyclic operations at each passage of the traveling brush units around the forward 15 ends of the shoes.

After the completion of the fourth cycle of operation, the Geneva gear again operates to move the cam 70 one step to the fifth position of the cam 70 during which time the roller 74 20 will occupy its intended position within the cam groove portion 78. Whereas the roller 74 will have been previously moved forwardly from its position shown in Figure 32 to occupy the positions 81 and 82, the roller will be moved rearwardly one step when it reaches the cam groove portion 78. This operation obviously swings the toe brush units bodily one step from the dotted line position shown in Figure 9, whereupon the brushes 151 will be brought into position over 30 the toe portions of the shoes. The length of the cam groove portion 78 is such as to maintain the toe brush units in the position last referred to through the fifth to the ninth cyclic operations inclusive. Thus the brushes 151 will 35 operate to polish the toe portions of the shoes throughout such cyclic operations except during the intermittent periods in which the cam 168 elevates the toe brush units to permit the traveling units to pass around the forward ends of the 40 shoes.

At the completion of the ninth cyclic operation, the Geneva gear transfers the roller 74 to the cam groove portion 76, and the roller 74 moves forwardly while passing between the 45 points 79 and 84. The roller 74 remains in the cam groove portion 76 throughout the rest of the operation of the apparatus, namely, through the tenth to the fourteenth operations inclusive. The movement of the roller from the cam groove 50 portion 78 to the portion 76 moves the roller 74 and associated parts one step, thus moving the brushes 151 out of their previous positions over the shoes and moving the buffing brushes 152 into proper positions over the shoes. The buffing brushes preferably are in the form of lamb's wool pads in order that a high gloss may be imparted to the toe portions of the shoes. The buffing operation takes place throughout the tenth to the fourteenth cyclic operations inclusive except 60 during the periods in which the toe brush units are elevated by the operation of the cam 168.

The cam 70 carries the pin 86 secured to the lug 85. Referring to Figure 39 it will be noted that when the apparatus approaches the conclusion of its operations, the pin 86 will engage the arm 525, thus moving this arm upwardly. At the completion of the fourteenth cycle of operation, the cam wheel 70 is advanced by the Geneva gear, and at such time, the arm 525 partakes of its last increment of movement, thus escaping over the pin 86 to return to its normal position, and at the same time kicking open the magnet operated switch. The magnet switch has been only generally illustrated in Figure 9 75

inasmuch as it is a conventional switch forming no part of the present invention per se, and it will be apparent that any suitable type of switch may be employed. Thus the circuit through the 5 magnet operated switch will be broken and the machine will automatically stop pending subsequent operation. Accordingly it will be apparent that it is merely necessary for a user of the apparatus to take his position on the seat 10 11, place his feet on the foot rests 19 and insert the proper coin in the coin chute, whereupon the operation of the apparatus is automatically initiated and continues throughout the various cyclic operations of the apparatus, preferably but 15 not necessarily fourteen in number, as described. At the end of the fourteenth cycle of operation, the apparatus will automatically stop until its operation is again initiated in the manner stated. The lug 85 may be utilized, if desired, for operating a counter of any suitable type to provide 20 a check on the apparatus, as will be apparent.

The polish reservoir for the toe brush units and the reservoirs for the traveling brush units are substantially identical and only one need be 25 referred to in detail. The reservoir for the toe brush units is illustrated in Figures 26, 27 and 28. When the reservoir is empty, the casing 410 is unscrewed from the flange 413, whereupon the threaded nozzle of a suitable polish supply means 30 is threaded into the opening 415 and the polish is fed into the reservoir. Under such conditions, the boss 433 will be arranged in the position shown in Figure 26, within the notch 432. Under such conditions the interior parts of the 35 reservoir will occupy the positions shown in Figure 28, with the plunger 417 contacting with the head 425 and slightly spaced from the ring 429. The polish material employed is preferably semi-plastic, being thin enough to flow and the reservoir 40 is filled while in an inverted position. A small vent opening is provided adjacent the opening 415, as shown in Figure 28, to permit the escape of air while the polish material is flowing into the reservoir. When the ring 412 is 45 then screwed into the flange 413, the vent opening will be closed by engagement with the seat 443.

After the ring 412 is threaded into the flange 413 the casing 411 is rotated to move the lug 433 into vertical alinement with the longitudinal slot 430, whereupon the casing 411 is moved inwardly to telescope with respect to the casing 410. The reservoir is now full of polishing material and such material prevents the plunger 417 from 50 moving inwardly with the casing 411. The movement of the latter accordingly takes place against the tension of the spring 428, and the stem 422 moves with the casing 411. Upon inward movement of the stem 422, this element will displace 55 polish material in the reservoir. As previously stated, the plunger 417 is spaced from the ring 429 when the reservoir is filled and the displacement of polishing material by the stem 422 and head 425 causes the plunger 417 to move outwardly into engagement with the ring 429. The casing 411 is then rotated to move the lug 433 into the notch 431 and is then released to occupy the dotted line position shown in Figure 26.

The notch 431 and the notch 380 of the reservoir unit for the traveling brush units are slightly undercut, as shown in Figures 23 and 26. This construction is provided merely to prevent turning movement of the casings 359 and 411. The play between the lug 433 and outer limit of the notch 431 permits inward movement of the cas-

ing 411 when the reservoir casing 410 is emptied in order to move the plunger 417 into engagement with the contact 469. It will be apparent that when the parts are assembled in the manner described when the reservoir 410 is filled, the 5 head 425 will occupy a position slightly within the recess 416, while the plunger 417 will be substantially in engagement with the ring 429.

As the apparatus is successively used, the casing 411 and stem 422 remain stationary, while 10 the plunger 417 moves inwardly under the influence of the tension of the spring 428 whenever polishing material is being pumped. This action continues until the plunger 417 finally comes into contact with the head 425 when the reservoir is nearly empty. Further operation of the plunger 417 under the influence of the partial 15 vacuum created by the pump plungers 444 when they move outwardly to take a new charge of polishing material into the passages 439 and 459 causes the plunger 417 to move inwardly carrying with it the head 425. This movement is transmitted through the stem 422 to the casing 411, and this element accordingly moves inwardly whereupon the flange 476 engages the plunger 20 413 to move the plunger 417 into engagement with the contact 469. This operation completes the parallel circuits through the solenoid 491 and the signal 531, thus preventing the collection 25 of any further coins in the manner previously described. The final inward movement of the casing 411 is permitted by the play between the lug 433 and the extremity of the notch 431.

From the chart illustrated in Figure 40, the 30 various cyclic operations of the apparatus can be readily determined. This chart illustrates the successive fourteen cycles of operation and the periods of operation of the various elements are shown. In the top row of the chart, the circulating brush unit as a whole is designated, and 35 each of these units makes fourteen complete cyclic operations around its orbital path. The periods at which the circulating brush unit passes around the heel and toe portions of the shoe is indicated, the unit being at the toe portion at the 40 beginning of each cycle of operation. Beneath the circulating brush unit, the polish-applying or blacking brush of such unit is indicated. This brush is out of operation during the first 45 two complete cycles of operation and starts to move into operative position during the third cycle. The brush referred to is in its innermost position during nearly all of the fourth cycle of operation and starts to move outwardly during the fifth cycle. After reaching its outermost 50 position it remains in such position during the remainder of the operation of the apparatus.

Beneath the blacking brush the blacking pump 55 is indicated on the chart and it will be noted that this pump operates during the third and fourth cycles of operation and is inoperative during all the other portions of the operation. From the chart it will be noted that the blacking pump operates somewhat in advance of the blacking brush, in that it starts to supply blacking to 60 such brush before the latter reaches its fully operative position and ceases to pump polishing material before the brush starts to move outwardly. Accordingly it will be apparent that the pump starts to charge the polish-applying brush 65 in advance of the actual operation of the polish-applying brush, while the latter continues to deposit its collected polish on the shoe after the pump has ceased to operate.

Beneath the pump on the chart, the cleaning 70

and polishing brush is indicated. This brush remains in operation throughout the fourteen cyclic operations and during the first two operations it cleans the shoe preparatory to the depositing of the polishing material thereon. During the time in which polish is being applied to the shoe, the polishing brush obviously follows the polish-applying brush and polishes the shoe as the polish is applied thereon. In this connection it will be noted that polish is applied during substantially two whole cyclic operations, and since the polishing brush remains in operation during such period, it may be considered that two coats of polish are applied to the shoe since the polishing brush follows rearwardly of the polish-applying brush. During the second cycle of operation of the polish-applying brush, therefore, polish will be applied over portions of the shoe which have been brushed by the polishing brush during the first cycle of operation of the polish-applying brush.

The next row on the chart indicates a toe brush unit as a whole. This unit is indicated as remaining elevated during the first two cycles of operation and the first portion of the third cycle of operation. The toe brush unit then successively drops and raises throughout the remaining portions of the operations of the apparatus, and it will be noted that the elevation of the toe brush unit occurs at the time when the circulating brush unit is passing around the toe portion of the shoe.

In the next row on the chart the intermittent cam is indicated, namely, the cam 70. During substantially the first two cycles of operation this cam holds the toe brush unit in position with the brush 150 thereof collecting polish, and near the end of the second cycle of operation and during the first portion of the third cycle the intermittent cam indexes the toe brush unit to a position wherein the polish-applying brush is arranged over the shoe. The next operation of the cam referred to occurs during the latter part of the fourth cycle of operation and the first part of the fifth cycle, and during such time indexes the toe brush unit to a position with the polishing brush 151 over the shoe. The third operation of the intermittent cam occurs during the latter portion of the ninth cycle of operation and the first portion of the tenth cycle, and operates to index the toe brush unit to a position with the buffer 152 arranged over the shoe.

The interference cam is indicated on the chart as being operative during the first two cycles of operation and during this period it holds the toe brush units elevated. At the end of the second cycle, the interference cam becomes inoperative for the remaining series of operations, and from the third through the fourteenth cycles of operation the toe brush unit is intermittently raised and lowered by the cam 167 in the manner previously described.

As previously described, the polish-applying brushes 150 of the toe brush units and the pump 65 for supplying polish thereto operate during the first two cycles of operation. Such operations are indicated on the chart, and it will be noted that during portions of the third and fourth cycles of operation, the polish-applying brush becomes operative for applying polish to the shoe. The latter operation occurs during those periods in which the traveling brush unit is at the sides and rear of the shoe. The polish-applying brush is idle from the last portion of the fourth cycle of 75 operation through the remaining operation of the

apparatus while the polish pump for the toe brush units is inoperative throughout the third to the fourteenth cycles.

The polishing brush of each toe brush unit is indicated as being idle during the first four cycles of operation. During such cycles, the polish-applying brush of the toe brush unit collects polish during the first two cycles and applies it during the third and fourth cycles. The polishing brush then comes into operation intermittently 10 during the fifth, sixth, seventh, eighth and ninth cycles, the polishing action occurring during the portions of these cycles in which the traveling brush units are away from the toe portions of the shoe. Throughout the tenth to the fourteenth 15 cycles of operation, the polishing brush is idle, and during such cycles of operation, the lamb's wool pad or buffing brush comes into operation. The buffer, as in the cases of the polish-applying and polishing brushes of the toe brush units, is inoperative while the traveling brush units are passing around the toe portions of the shoes and are operative during the remaining portions of the cycles of operation referred to.

Thus the complete polishing of the shoes is accomplished at the end of the fourteenth cycle, whereupon the apparatus is automatically stopped. In the lowermost row of the chart the "miscellaneous movements" are set forth, and these movements include the automatic stopping 30 of the machine and the operation of the counter. As previously stated, the pin 86, carried by the cam 70 engages the switch arm 525 to release the magnet operated switch at the end of the fourteenth cycle of operation. The lug 85 which carries the pin 86, may be utilized for operating a counter whereby the exact number of operations of the apparatus may be determined.

From the foregoing it will be apparent that the present apparatus is fully automatic in operation 40 for cleaning the shoes, applying polish thereto, and then polishing the shoes, the various operations occurring automatically and successively without any attention on the part of the user. The various functions of the apparatus are cam 45 controlled, and no chains or other noisy transmission means are employed. Accordingly the apparatus is not only highly efficient and automatic in operation but is also extremely quiet. The automatic features of the operation include 50 the prevention of the operation of the apparatus when the polish reservoirs do not contain sufficient polish to complete proper operation of the apparatus and it is impossible for the apparatus to operate until the user has taken his position 55 on the seat 11. After the apparatus has completed its various automatic functions and stops, the user may leave the seat 11, whereupon the coin paddle 489 will be restored to normal position to deflect any inserted coins unless the seat 60 11 is again occupied and the polish reservoirs contain a sufficient amount of polish for another operation.

It is to be understood that the form of the invention herewith shown and described is to be 65 taken as a preferred example of the same and that various changes in the shape, size and arrangement of parts may be resorted to without departing from the spirit of the invention or the scope of the subjoined claims.

I claim:

1. Shoe polishing apparatus comprising a traveling brush unit, means for guiding said unit for movement in an orbital path around a shoe, and power means for effecting successive cyclic move- 75

ments of said unit around its path, said unit comprising a polishing brush in constant engagement with the shoe, a polish-applying brush, means for supplying polish to said latter brush, and common control means for said last named means and said polish-applying brush for supplying polish to said latter brush, effecting movement of said latter brush into engagement with the shoe, holding it in such position for at least 10 one cyclic movement of said unit and then moving it out of engagement with the shoe prior to the completion of said cycles of operation of said unit.

2. Shoe polishing apparatus comprising a traveling brush unit, means for guiding said unit for movement in an orbital path around a shoe, and power means for effecting successive cyclic movements of said unit around its orbital path, said unit comprising a polishing brush in constant 20 engagement with the shoe, a polish-applying brush, means for supplying polish to the latter brush including a positive pump, and control means for rendering said pump operative and for effecting movement of said polish-applying brush 25 into engagement with the shoe, holding it in such position for at least one cyclic movement of said unit and then moving it out of engagement with the shoe and simultaneously rendering said pump inoperative, prior to the completion of said cycles 30 of operation of said unit.

3. Shoe polishing apparatus comprising a traveling brush unit, means for guiding said unit for movement in an orbital path around a shoe, and power means for effecting successive cyclic movements of said unit around its orbital path, said unit comprising a polishing brush in constant engagement with the shoe, a polish-applying brush, means for supplying polish to the latter brush including a positive pump, common transmission 40 means for said polish-applying brush and said pump and including a normally disengaged clutch, control means for effecting movement of said polish-applying brush into engagement with the shoe, holding it in such position for at least one 45 cyclic movement of said unit and then moving it out of engagement with the shoe prior to the completion of said cycles of operation of said unit, and means operative upon movement of said polish-applying brush into engagement with the 50 shoe for rendering said clutch operative.

4. Shoe polishing apparatus comprising a traveling brush unit, means for guiding said unit for movement in an orbital path around a shoe, and power means for effecting successive cyclic movements of said unit around its orbital path, said unit comprising a polishing brush in constant engagement with the shoe, a polish-applying brush, means for supplying polish to the latter brush including a positive pump, power transmission 55 means connected between said power means and said polishing brush, power take-off means for connecting said power transmission means to said pump and said polish-applying brush and including a clutch, and control means operative for effecting movement of said polish-applying brush into engagement with the shoe, holding it in such position for at least one cyclic movement of said 60 unit and then moving it out of engagement with the shoe prior to the completion of said cycles of operation of said unit, and means for rendering said clutch operative during the period of operation of said control means.

5. Shoe polishing apparatus comprising a traveling brush unit, a guideway for said unit defining an orbital path around a shoe, and power

means for effecting successive cyclic movements of said unit around said guideway, said unit comprising a carrier, a support pivoted to the carrier, a polishing brush carried by said support, spring means urging said polishing brush into engagement with a shoe arranged within said orbital path, a second support pivoted to said carrier, a polish-applying brush carried by said latter support, means for supplying polish to said latter brush, spring means tending to urge said latter brush into engagement with the shoe, and control means normally holding said polish-applying brush out of engagement with the shoe and operative for releasing it during at least one cyclic movement of said unit and then moving it out of engagement with the shoe and holding it in such position during the remaining cyclic movements of said unit, said polish-applying means comprising a positive pump, common drive means for said pump and said polish-applying brush including a normally inoperative clutch, and means for rendering said clutch operative when said polish-applying brush is released for movement into engagement with the shoe.

6. Shoe polishing apparatus comprising a traveling brush unit, a guideway for said unit defining an orbital path around a shoe, and power means for effecting successive cyclic operations of said unit around its path, said unit comprising a drive shaft extending vertically through said guideway, 30 a carrier rotatably supporting said shaft and having rollers engaging in said guideway, a pair of supports pivoted to said shaft, a polishing brush carried by one support, a polish-applying brush carried by the other support, constantly operating drive means between said drive shaft and said polishing brush, power driven polish supplying means for said polish-applying brush, drive means for connecting said drive shaft to said polish-applying brush and for rendering said polish supplying means operative, said last named drive means including a normally inoperative clutch, and control means for effecting inward movement of said second named support to bring said polish-applying brush into engagement with the 45 shoe, holding it in such position for at least one cyclic movement of said unit and then moving it out of engagement with the shoe prior to the completion of said cycles of operation of said unit, said control means being operative for effecting 50 engagement of said clutch during at least the first part of the period in which said polish-applying brush is in engagement with the shoe.

7. Shoe polishing apparatus comprising a traveling brush unit, means for guiding said unit for movement in an orbital path around the shoe, power means for effecting successive cyclic movements of said unit around its path, said unit comprising a polishing brush in constant engagement with the shoe, a polish-applying brush, cam control means for said polish-applying brush operative for maintaining it out of engagement with the shoe during at least the first cyclic operation of said unit, effecting movement of the polish-applying brush into engagement with the 60 shoe and holding it in such position for at least one cyclic operation of said unit and then holding it out of engagement with the shoe during the remaining cyclic operations of said unit, power driven means for supplying polish to said polish-applying brush, and automatic means for rendering said last named means operative during at least the first portion of the period in which said polish-applying brush is in engagement with the shoe.

8. Shoe polishing apparatus comprising a traveling brush unit, means for guiding said unit for movement in a horizontal orbital path around a shoe, power means for effecting successive cyclic movements of said unit around its path, a vertically movable toe brush unit operative horizontally over and biased downwardly for engagement with the toe portion of the shoe, means for holding said toe brush unit in elevated position during at least one complete cyclic operation of said traveling brush unit, and means operative thereafter for elevating said toe brush unit during the periods of successive cyclic operations of said traveling brush unit in which said latter unit is moving around the toe portion of the shoe.
9. Shoe polishing apparatus comprising a traveling brush unit, means for guiding said unit for movement in a horizontal orbital path around a shoe, power means for effecting successive cyclic movements of said unit around its path, a vertically movable toe brush unit operative horizontally over and biased downwardly for engagement with the toe portion of the shoe, said toe brush unit including a polish-applying brush and a polishing brush, means for supporting said toe brush unit in elevated position during the period of at least the first cyclic operation of said traveling brush unit, means for supplying polish to said polish-applying brush during such period, means for holding said toe brush unit in a position with said polish-applying brush arranged over the toe portion of the shoe during a succeeding period of operation, means for holding said toe brush unit in a position with said polishing brush arranged over the toe portion of the shoe during the period of the remaining cyclic operations of the traveling brush unit, means for effecting horizontal movement of said toe brush unit during all of said periods of operation, and means for elevating said toe brush unit during all of its periods of operation except the first period, when the traveling brush unit is passing around the forward end of the shoe.
10. A toe brush unit for shoe polishing apparatus comprising a horizontally movable body, a polishing brush and a polish-applying brush carried by said body, means for constantly moving said body horizontally, means for supplying polish to said polish-applying brush, means for bodily shifting said body horizontally to a first position with said polish-applying brush in cooperative engagement with said polish supplying means, then to a second position with said polish-applying brush in engagement with the toe portion of the shoe, and thereafter to a third position with said polishing brush in engagement with the shoe, and means automatically operative when said body is in its first named position for rendering said polish supplying means operative.
11. A toe brush unit for shoe polishing apparatus comprising a body, means for supporting said body for oscillatory and bodily movement about a vertical axis, a polishing brush and a polish-applying brush carried by said body, means operative for supplying polish to said polish-applying brush, means for bodily shifting said body to a first position with said polish-applying brush in cooperative engagement with said polish supplying means, then to a second position with said polish-applying brush in engagement with the toe portion of a shoe, and then to a third position with said polishing brush in engagement with the shoe, means automatically operative when said body is in its first position for rendering said polish supplying means operative, and means for constantly oscillating said body in all of its positions.
12. A toe brush unit for shoe polishing apparatus comprising a substantially horizontal body, a supporting shaft for said body mounted for vertical and oscillatory movement, means for constantly oscillating said body about the axis of said shaft, a polishing brush and a polish-applying brush carried by said body, means for elevating said shaft, a polish-supplying device, means for bodily shifting said body during oscillatory movement thereof from a first position with said polish-applying brush arranged over said polish-supplying device to a second position with said polish-applying brush in engagement with the toe of a shoe and then to a third position with said polishing brush in engagement with the shoe, and means for holding said body elevated when in its first named position with said polish-applying brush in engagement with said polish-supplying device and for lowering said body as the latter is shifted to its second named position.
13. A toe brush unit for shoe polishing apparatus comprising a body, a vertical shaft for supporting said body for oscillatory and bodily movement about a vertical axis, means for supporting said shaft for vertical movement, means for elevating said shaft from a normal to a higher position, a polishing brush and a polish-applying brush carried by said body, means for supplying polish to said polish-applying brush when said shaft is elevated and said body is in a given position, a vertically elongated gear carried by said shaft, and means for transmitting oscillatory and bodily shifting movement to said shaft, said last named means including a second gear meshing with said first named gear and fixed against vertical movement, said second gear being constantly oscillated and being bodily shiftable around its axis to shift said body from said first named position to a second position with said polish-applying brush in contact with the toe portion of the shoe when said body is in its normal position and to a third position with said polishing brush in engagement with the toe portion of the shoe.
14. A toe brush unit for shoe polishing apparatus comprising an arcuate body, means for supporting said body for oscillation and bodily movement about a vertical axis, a polish-applying brush and a polishing brush carried by said body, means for supplying polish to said polish-applying brush, a longitudinally movable rack, gearing connected between said rack and said body, a lever having connection at one end with said rack, a pivotal support for said lever connected to the latter intermediate its ends, means connected to the other end of said lever for transmitting constant oscillatory movement thereto, means for shifting the pivot support of said lever to bodily shift said body during oscillation thereof from a position with said polish-applying brush in engagement with said polish supplying means, then to a second position with said polish-applying brush over and in engagement with the toe portion of a shoe, and then to a third position with said polishing brush in engagement with the shoe, and means automatically operative when said body is in its first position for rendering said polish supplying means operative.
15. Polish supplying means for the polish-applying brush of a shoe polishing apparatus comprising a reservoir formed of a pair of telescoping casing sections, a casing having an orifice engageable by the polish-applying brush

a pump connected to said reservoir and to said casing to transmit polish from the former to the latter, a plunger in one of said casing sections, a spring acting between said plunger and the other casing section to tend to displace polish from the first named casing section, means for latching said casing sections against longitudinal movement in relatively extended position to permit the supplying of polish to said first named casing section, and means for latching said casing sections in relatively collapsed position to compress said spring.

16. Polish feeding means for a shoe polishing apparatus comprising a polish reservoir having an outlet passage adjacent one end thereof, a plunger in said reservoir forming one wall thereof, spring means urging said plunger toward said outlet passage, and a pump operable for withdrawing polish through said outlet opening.

17. Polish feeding means for a shoe polishing apparatus having a power source, comprising a pair of telescoping casing sections normally arranged in a fixed position with respect to each other, one of said casing sections forming a reservoir having an outlet opening, a plunger forming one wall of said reservoir, spring means urging said plunger toward said outlet opening, a pump operative for withdrawing polish through said outlet opening, means operative for transmitting movement from said plunger to the other casing section after said plunger has moved a predetermined distance toward said outlet opening, and means for utilizing movement of said second named casing section for rendering said power source inoperative.

18. In a shoe polishing apparatus, a polishing unit comprising a polish-applying brush and a polishing brush movable in engagement with a shoe, a polish reservoir having a relatively movable portion, means for transferring polish from said reservoir to said polish-applying brush, a power source for operating said polishing unit, means operative prior to the complete emptying of the reservoir for transmitting movement to the relatively movable portion of said reservoir, and means operative upon movement of such

relatively movable portion for preventing operation of said power source.

19. In a shoe polishing apparatus, a polishing unit comprising a polish-applying brush and a polishing brush movable in engagement with a shoe, a reservoir formed of a pair of telescoping casing sections, a head carried by the free end of one casing section and provided with a polish passage therethrough, a casing having an orifice engageable with said polish-applying brush, a pump means for delivering polish from said passage to said casing, a plunger movable in said first named casing section, a spring acting between said plunger and the other casing section to tend to urge said plunger toward said passage, means carried by said second casing section and engageable by said plunger as the latter approaches said passage to transmit movement to said second casing section, said plunger being engageable with said last named means to transmit longitudinal movement to said second casing section prior to the complete emptying of the reservoir, a power source for the polishing apparatus, and means operative when said plunger transmits movement to said second casing section for preventing operation of said power source.

20. Shoe polishing apparatus comprising a base, a shoe rest projecting upwardly from said base, said base being provided with a guideway forming an orbital path around said foot rest, a traveling brush unit including a member projecting upwardly through said guideway, means for operating said traveling brush unit and for effecting bodily movement thereof with said member moving through said orbital path, and flexible means forming a closure for said guideway and movable with said traveling brush unit.

21. Apparatus constructed in accordance with claim 20 wherein said flexible means comprises a plurality of plates operating over said slot and pivotally connected to each other, said plates having dependent means operating in said guideway to cause said plates to follow the path defined thereby.
